**CHARACTER RECOGNITION SYSTEM
HAVING ERROR DETECTION MEANS**

Frank R. Schmid, Gardena, Calif., assignor to The National Cash Register Company, Dayton, Ohio, a corporation of Maryland

Filed Nov. 19, 1962, Ser. No. 238,371
8 Claims. (Cl. 340—146.3)

The present invention is directed to character recognition systems and more particularly to improved character recognition systems which provide greater accuracy and reliability in the reading of characters.

Rapid development of character recognition systems which are capable of reading conventionally printed information has been due to the need for direct use of printed documents by computer systems without manual conversion of the information into computer language on punched paper tape or other record medium. It is of obvious benefit to be able to process records of business transactions, which are printed on ordinary paper stock, directly into computer systems without the need of manually converting the printed information into computer language.

One of the first considerations of a character recognition system is its reliability, and more particularly, the capability in the system of avoiding a substitution, during the reading, of one character included in a prescribed set for another character, included in the prescribed set, such that the error is difficult to detect. Although the possibility of such substitution may be guarded against, in part, by character configurations which make it difficult to misread one character as another character, when printing tolerances are loose and paper defects are present, the substitutions may still occur at a higher rate than can be tolerated in certain business procedures. Therefore, in a character recognition system which is intended to read directly the printing produced by normally acceptable business machine printing equipment, it is desirable to detect poor quality printing or foreign particles in paper which are located near printed characters, and to reject incorrect readings associated with these characters, since these incorrect readings are capable of producing errors which would otherwise be difficult to detect; particularly if the readings associated with these characters were to cause the system to indicate another character which is included in the prescribed set of characters which the system normally reads.

Character recognition systems have been developed which are capable of reading relatively poor quality printed characters and to provide suitable inputs for computer systems. Systems of this type have been disclosed in copending patent applications Serial No. 861,469, filed December 23, 1959, now Patent 3,102,995, and Serial No. 122,126, filed July 6, 1961, now Patent 3,217,294 assigned to a common assignee. In these systems, it was recognized that it is considerably less expensive to develop an optical character reading system which is capable of reading printed characters on documents in which the printing is of relatively poor quality, if the single character reading system is handling documents from a very large number of business machines, e.g. adding machines, cash registers, etc., in which considerable expense would be involved to provide high quality printing and paper therefor. For example, in conventional wheel-type printing equipment employed on many business machines, the weight and uniformity of the print varies, the spatial relationship of the characters is not uniform, and the characters may be skewed. In addition, the documents produced by printing equipment of business machines may contain marks due to ink splatter or foreign particles in the paper stock which could be

2

interpreted as portions of a character, or there may be gaps in the character lines or such variations in shading which appear as gaps in the lines of a character. Still further, the amplifiers and detectors and others electronic circuits in the systems can produce noise pulses which appear as character information so as to be capable of producing codes of characters other than the printed characters being read, i.e. produce a substitution of characters wherein one character is read as another different character. Although noise pulses produced due to the quality of printing or the electronic circuits of the system is normally to be expected, the occurrence of these noise pulses during the scanning of the critical areas surrounding the character in the reading process can be readily detected by a comparison of immediately succeeding scans of the character in systems which provide multiple scans of each character. While the generation of noise pulses during the scanning of critical areas of a character, which would cause substitution of one character for another, is infrequent and the characters are stylized to provide a code in which it is difficult for misregistration, skew, etc., to produce substitution of characters, the greatest care should be taken to avoid such substitution. Thus, it is important to detect the possibility of an error condition because of noise pulses which occur in critical places of character reading to avoid the possibility that a character may have been read incorrectly whereby the reading can be checked for accuracy. While the systems of the cited patent applications have been extremely successful in the reading of relatively poor quality printing, it has been found that increased accuracy and reliability is, in many instances, not only desirable but an absolute requirement. This higher degree of accuracy and reliability can be achieved in accordance with the system of the present invention by comparing information derived from successive scans of the same printed characters on the documents being read. Thus, in accordance with the improved character recognition system of the present invention, in which a character is scanned a plurality of times in the normal process of reading, the information obtained in successive scans can be recorded and compared to detect inconsistencies and substitution of one character for another character and also the substitution of characters in adjacent columns. If the comparison of information is not consistent, which indicates the possibility of an error in reading a character, the scanning of the character can be repeated until the information detected is consistent, or terminated after a predetermined number of attempts to read the character or characters. Thus, in accordance with the present invention the information obtained from predetermined scans, in multiple scanning of a character, is delayed for the time period between scans, e.g., by recording the information derived from these scans, and then compared to determine whether or not the information is inconsistent and consequently whether or not there is a possibility of error. In accordance with the preferred embodiment of the invention, only the signals including noise which are produced during the scanning of the critical areas of and about a character are compared with corresponding signals produced in the following scan in order to detect any inconsistency therein and therefore a possible error condition. Thus, if the scans are inconsistent, an error indication is provided which will prevent the substitution of characters, one for another, which could otherwise remain undetected. Accordingly, in predetermined successive scans of printed characters on a document, signals produced during scanning of critical areas of the document are magnetically recorded and reproduced whereby signals produced by immediately succeeding scans can be compared to detect inconsistencies therein whereby potential error conditions can be detected to avoid the pos-

sibility of errors, and more particularly, the possibility of substitution of one character for another character.

Accordingly, it is an object of the present invention to compare signals produced during the reading of characters and more particularly to compare signals generated during the reading of the characters in successive scans thereof to detect inconsistencies therein for the possibility of an error.

Another object of the present invention is to compare the signals generated in scanning printed characters in predetermined time intervals corresponding to predetermined critical areas of a document in successive scanning of each character.

A further object of the present invention is to provide a character recognition system in which the possibility of error in the reading of characters is detected even though a recognizable character code has been detected by the system.

A still further object of the present invention is to provide a character reading system in which an error signal is produced in response to different information being reproduced in predetermined successive scans of a character in order to prevent the substitution of one character for another character.

Another object of the present invention is to provide a character reading system in accordance with any or all of the foregoing objects, which provides for the recording of signals produced during scanning the area of the leading edge portion of each character and comparing the recorded signals with signals derived from at least one subsequent scan of the area near the leading edge of the same character to produce an error signal when the comparison indicates a discrepancy between the signals produced in the successive scans.

An additional object of the present invention is to provide a character reading system in accordance with any or all of the foregoing objects in which the possibility of reading characters incorrectly is minimized.

The above objects are accomplished in the typical embodiments of the present invention by means of a system generally similar to the system disclosed in the aforementioned copending patent application, Serial No. 122,126 except that substantial improvements in accuracy in the reading of characters are attained and a more reliable character recognition system has been provided as will be clear from the detailed description of the present invention which follows.

The specific nature of the present invention as well as other advantages, objects, and uses thereof will become apparent to those skilled in the art as disclosure is made in the following detailed description of a typical embodiment of the present invention illustrated in the accompanying drawing in which:

FIG. 1 shows a plurality of typical stylized characters for use in the typical embodiment of a character reading system in accordance with the invention described herein;

FIG. 2 illustrates a section of a typical paper tape having rows of stylized characters printed thereon;

FIG. 3 is a schematic diagram of a character reading system in accordance with the invention showing, in particular, the sensing and detecting means incorporated therein;

FIG. 4 is a block diagram of a typical portion of the detector circuitry shown in FIG. 3;

FIGS. 5 and 6 show the right end portion of a row of stylized characters on a typical paper tape and the various waveforms derived by the circuitry of FIG. 3 in response to the initiation of a scan and the intersection of a reference mark provided at the right end of each row;

FIG. 7 is a block and circuit diagram of a detailed embodiment of the character recognition unit shown in block form in FIG. 3;

FIG. 8 shows the relationship of a typical stylized character with respect to the program counts provided by

the program counter of FIG. 7, and with respect to the scanning apertures during a "read" scan;

FIG. 9 is a schematic diagram illustrating in detail the ten to five code converter of FIG. 7, showing in particular, the logical circuitry for producing the correct code signal V_c and the error code signal V_e ;

FIG. 10 is a schematic diagram of the preferred embodiment of the substitution error detector means of the present invention showing the means for delaying and then comparing certain signals generated in the improved character recognition system;

FIG. 10a is a circuit diagram of the error holdover circuit shown in block diagram in FIG. 10;

FIG. 11 is a graph which shows, greatly enlarged, a portion of the typical tape shown in FIG. 2 with characters printed thereon together with the waveforms of signals generated in successive scans of the characters to illustrate the operation of the present invention in detecting character substitution errors; and

FIG. 12 is a section of tape showing a row of characters printed as shown which characters are scanned by reversing the direction of rotation of the scanning drum indicated in FIG. 10.

Referring now to the drawings, wherein like reference numerals designate like or corresponding parts throughout the several views, a set of sixteen stylized characters are illustrated in FIG. 1 which are recognizable by the typical character recognition system in accordance with the invention.

As shown in FIG. 1, the sixteen characters comprise decimal digits "0" through "9" and six additional characters or symbols. Each character is divided into five vertical zones, U, V, W, X, and Y, one or more of which zones contain character information in the form of vertical segments or lines used in forming the character. It will be understood that the lines in FIG. 1 designating the zones, U, V, W, X, and Y, are provided merely for illustrative purposes and would not appear on actual printed characters.

The horizontal paths in FIG. 1 designated r_t and r_b passing through the top and bottom halves of each character, such as the character "0," indicate the two properly located scanning paths across zones U, V, W, X and Y for which the presence or absence of a vertical segment in each zone is detected in order to obtain character information from which the character can be identified. If the presence of a vertical character segment in a zone is designated as a binary "1," and the absence of a character segment in a zone is designated as a binary "0" then, if a character is scanned along the top and bottom paths r_t and r_b as indicated, a five-digit binary number will be obtained for each path as shown below each character in FIG. 1. The two five-digit binary numbers thus obtained may be considered as a ten-digit binary number, the stylizing of the characters in the system being such that a different ten-digit binary number is obtained for each character.

The stylizing of the characters in the system is chosen to be such that two reading errors are required in order to mis-identify a character, i.e. substitution of one character for another. For example, in scanning the letter "O" in FIG. 1, if the vertical segment in zone U of the scan along the path r_t were absent because of improper printing, the five-digit binary number obtained for the top scan along path r_t would be 10000 instead of 10001. An examination of the other characters in the system will reveal that there is no other character in the system having the five-digit binary number 10000 for the top scan along path r_t which also has the five-digit binary number 10001 for the bottom scan along path r_b . Thus, an error of this type can be recognized and would not cause the character to be mistaken for any other character in the system. It will also be noted in FIG. 1, that each character is stylized so that a vertical segment is provided in zone U in either or both of the paths r_t or r_b . This is

done to permit accurate control of horizontal registration, as will hereinafter become evident.

Before continuing the detailed description of FIGS. 2 to 9, it should be noted that the description which follows is also set forth in substantially the same manner in the cited copending patent application Serial No. 122,126. The details of the improved character recognition system of the present invention are set forth in FIGS. 10 to 12 of the drawings and the section of this specification entitled "Character Substitution Error Detection." Those familiar with the above cited copending application are referred directly to this section of the disclosure for a description of the improved character recognition system of the present invention.

Referring now to FIG. 2 a typical section of paper tape 12 from a cash register, adding machine or other business machine is shown having rows of stylized characters printed thereon, the stylizing being in accordance with FIG. 1. It will be noted that a vertical line or reference mark 46 is located to the right of each row of characters and extends vertically above portions of the characters in each row. While the provision of such a reference mark 46 is not essential, it does offer certain advantages which make its use desirable as will hereinafter become evident. The first row of characters 44 shown on the tape 12 in FIG. 2 is typical of a complete row of characters in which no misregistration or printing errors in the characters is visibly noticeable. The second row 48 on the tape 12 in FIG. 2 illustrates a group of characters having both vertical and horizontal misregistration, the characters "4," "7," and "1" being misaligned vertically, and the characters "3" and "9" having excessive spacing therebetween. The last two rows of characters on the tape 12, rows 52 and 54, each illustrate a situation where a portion of one of the characters on the row is absent because of improper printing. In row 52, a portion of the character "7" is missing while, in row 54, the entire lower portion of the character "2" is missing. The manner in which these typical rows of characters in FIG. 2 are read in the system of the present invention will become evident from the typical embodiment of the invention to be described herein.

Initially, it will be helpful to briefly summarize the overall operation of the typical embodiment to be described herein, as a result of which, rows of characters such as illustrated in FIG. 2 are read. First, each row of characters is progressively scanned by successive sweeps across the row as the tape 12 is moved relatively slowly past a scanning station in the direction indicated by the arrow 11 in FIG. 2; e.g. the top portion of the characters of the first row are scanned first and in subsequent sweeps the remainder of the characters in the row are scanned. A "read" scan is then performed on each character in the row, independently of the other characters in the row, when each character has moved to a position so that scanning is approximately along the proper paths r_t and r_b shown in FIG. 1 and a record is made of each character read. After all eight characters on a row have been read and recorded scanning is temporarily halted while the characters in the row are read-out into the suitable output equipment, the manner of character read-out being determined in accordance with a particular one of the characters in each row, specifically, the character nearest the reference mark 46. Employing such a procedure for read-out, the characters in row 44 in FIG. 2 would then be outputted in accordance with the character "I-□" in the row, the characters in row 48 and 54 would be outputted in accordance with the character "P," and the characters in row 52 would be outputted in accordance with the character "Y." Another operating feature of the typical embodiment of the invention to be described herein is that, if an error is detected in a particular row, the row is re-scanned in an attempt to obtain a proper reading and, if after eight re-scans a correct reading cannot be obtained, an error signal is out-

putted, the row containing the error is marked to indicate where the error occurred, and scanning then proceeds to the next row.

Referring now to FIG. 3, a schematic representation is illustrated of an embodiment of an optical character reading system in accordance with the invention showing, in particular, the optical scanning and detecting means incorporated therein. As shown, a paper tape 12, such as illustrated in FIG. 2, is mounted for movement on a tape transport 14. A drive capstan 16 of the tape transport 14 is coupled to a synchronous motor 13 to move the tape 12 at a desired speed past the face of a forming head 19, which face defines a scanning station 17 for the tape 12.

By means of an optical lens 28, an image of the section of the tape 12 at the scanning station 17 is formed on the outer periphery of a rotating drum 20, which serves as the scanning means of an optical detector 10. The drum 20 is suitably coupled to a synchronous motor 40 to rotate the drum 20 at a desired speed. In order that the image formed on the rotating drum 20 will be in focus for the entire length of the row of characters extending across the width of the tape 12, the curved face of the forming head 19 is made to conform to the curvature of the drum periphery, and the section of the tape 12 at the scanning station 17 is maintained against the curved face of the forming head 19 by perforations leading to a vacuum chamber provided in the head 19.

The rotating drum 20 is provided with eighteen identical groups of apertures equally spaced around the drum periphery, each group comprising four diamond-shaped apertures, such as illustrated by numerals 22a, 22b, 22c, and 22d in FIG. 3 for one such group. Interposed between the drum 20 and the lens 28 is a stationary shroud 24 surrounding a portion of the drum periphery and having a viewing slot or window 23 therein of sufficient size to permit a row of characters to be imaged on the drum periphery, the resulting image then being simultaneously scanned along four lateral paths by each group of four apertures as the group traverses the window 23.

Four light beam guides 26a, 26b, 26c and 26d, formed of Lucite rods, for example, are positioned adjacent the inner peripheral surface of the drum 20 opposite the window 23 in the shroud 24 so as to correspond to apertures 22a, 22b, 22c, and 22d respectively. Changes in light level produced as each group of apertures 22a, 22b, 22c, and 22d scans the image on the rotating drum 20 are then transmitted through the respective beam guides 26a, 26b, 26c, and 26d to photosensitive elements 30a, 30b, 30c, and 30d, respectively. These photosensitive elements 30a, 30b, 30c, and 30d are responsive to light variations appearing in their respective beam guides 26a, 26b, 26c, and 26d to produce respective electrical signal outputs a , b , c , and d which are fed to character detector circuitry 32, as shown in FIG. 3.

The detector circuitry 32 is constructed and arranged to provide five output signals A, B, C, D, and S in response to the four input signals a , b , c , and d applied thereto. The signals A, B, C, and D consist of pulses of predetermined magnitude and duration derived from input signals a , b , c , and d , respectively. Each of the pulses of the signals A, B, C, and D, thus, represent the detection of a vertical character segment by its respective aperture 22a, 22b, 22c, or 22d. Since only the presence or absence of a character segment in each zone need be detected because of the stylizing employed, the apertures 22a, 22b, 22c, and 22d may be made sufficiently large so that the detector circuitry 32 can more easily distinguish character segments from minor imperfections in the paper, or from other minor extraneous marks. Preferably, the apertures 22a, 22b, 22c, and 22d are of diamond-shape, as shown in FIG. 11a, with a transverse dimension equal to the average width of a vertical character segment. In such case, the signals resulting from a great majority of foreign matter or spurious marks on

the paper will represent only a relatively small percentage of the total area viewed by an aperture while, on the other hand, the signal resulting from a vertical character segment will represent the greater percentage of the total area viewed, thereby facilitating the distinguishing of character segments from the great majority of the other extraneous marks.

Before continuing with the description of the embodiment of FIG. 3, reference will be made to FIG. 4 to illustrate how the detector circuitry 32 is capable of producing output signals A, B, C, and D whose shaped pulses accurately represent the detection of vertical character segments by their respective apertures 22a, 22b, 22c, and 22d.

Referring to FIG. 4 it will be seen that a typical portion of the detector circuitry 32 includes an amplifier 155 which amplifies an input waveform, such as the waveform b obtained in response to the detection of a vertical character segment, and adjusts its clipping level to eliminate noise, thereby producing the resultant signal waveform 164. The signal waveform 164 is next differentiated in differentiating circuit 156 to provide the signal waveform 166. The signal 166 is then amplified in amplifier 157 and coupled to the input of a blocking oscillator 158, which circuits are so constructed and arranged to cause the shaped output pulse B to appear at the output of the blocking oscillator 158 in response to the negative-going zero crossing of the differentiated waveform 166.

It should be noted that, by deriving each output pulse (e.g. pulse B) in response to the negative-going zero crossing of its differentiated detected waveform, each output pulse will occur substantially at the center line of its corresponding vertical segment regardless of its width. This most advantageous result is of great value in obtaining accurate horizontal registration, as will hereinafter become evident, and is achieved because the print of a vertical segment inherently grows lighter by equal amounts on each side of its center line; consequently, the negative-going zero of the differentiated waveform, in response to which the output pulse representing the segment is produced, necessarily occurs substantially at the center line of the vertical segment.

Having described the derivation of a typical pulse which is typical also of signals A, C and D, the description of the FIG. 3 embodiment of the invention will now be continued. It will be noted in FIG. 3 that, in addition to the signals A, B, C, and D, detector circuitry 32 provides a fifth output signal S. This output signal S is produced by the detector circuitry 32 in response to the abrupt change in the intensity of light seen by all four of the apertures 22a, 22b, 22c, and 22d as each group of apertures leave the darkness of the shroud 24 and move into the light of the window 23. At such a time, a large amplitude signal is produced by each of the respective photosensitive elements 30a, 30b, 30c, and 30d, in response to which, a unique pulse S can be produced by the detector circuitry 32, which preferably is chosen to have the same magnitude and duration as the pulses of signals A, B, C, and D (such as illustrated at B in FIG. 5). Each pulse S, therefore, may then be conveniently used to indicate the beginning of each scan of a row of characters.

Besides the signals A, B, C, D, and S obtained at the output of the detector circuitry 32, additional signals N₁', B_R, B_R', and T₁' are also required in the typical embodiment of FIG. 3. These additional signals provide information relating to the detection of the reference mark 46 (FIG. 2) at the right end of each row, and may conveniently be derived from the signal S (which is a pulse appearing at the start of each scan) and the signal B (which produces a discrete pulse each time a vertical character segment, or reference mark, is detected by the aperture 22b). The derivation of these additional signals N₁', B_R, B_R', and T₁' as well as their significance will be better understood by reference to FIGS. 5 and 6 along with FIG. 3.

In FIGS. 5 and 6, a portion of a row of characters on the tape 12 is shown, the shroud 24 being cut away to better illustrate the apertures 22a, 22b, 22c, and 22d, which are shown in a position such that they will shortly leave the shroud 24 and enter the area of the window 23 to begin another scan of a row of characters. Also shown in FIGS. 5 and 6, below the tape 12 are waveforms which illustrate the derivation of the signals N₁', B_R, B_R', and T₁', the waveforms in FIG. 5 representing the situation where the aperture 22b intersects the reference mark 46, and the waveforms in FIG. 6 representing the situation where the aperture 22b fails to intersect the reference mark 46.

Referring now to FIG. 3 along with FIGS. 5 and 6, it will be seen that the signal S is fed to the set input t₁ of a normally false one-shot T1 and to the set input n₁ of a flip-flop N1. Thus, as shown in the corresponding waveforms S, T1 and N1 in FIGS. 5 and 6, at the appearance of the pulse S (when the apertures 22a, 22b, 22c, and 22d leave the shroud 24), both the one-shot T1 and the flip-flop N1 are switched to their true state, as indicated in FIGS. 5 and 6 by their respective true outputs T₁ and N₁ becoming more positive (positive representing true and zero representing false). While only the waveforms for the true outputs T₁ and N₁ of flip-flops T1 and N1 are shown in FIGS. 5 and 6, it will be understood that the false outputs T₁' and N₁' will always be in a state opposite to the state of their respective true outputs T₁ and N₁. The time for which the one-shot T1 remains true before returning to its false state is chosen in accordance with the maximum time allowed for the reference mark 46 to be intercepted if it is in the path of aperture 22b.

The signal B from the detector circuitry 32 is fed to an "AND" gate 52 along with the true output T₁ of the one-shot T1. Thus, as will be understood from the corresponding waveforms T1, B, and B_R in FIGS. 5 and 6, an output pulse B_R is obtained from "AND" gate 52 only if a pulse is produced by signal B while T₁ is true; that is, if aperture 22b intercepts the reference mark 46 before one-shot T1 returns to its false state. In FIG. 5, aperture 22b intercepts the reference mark 46 so that a pulse B_R is produced at the output of "AND" gate 52. However, in FIG. 6, no signal B_R is produced, since aperture 22b does not intercept the reference mark 46. Thus, a pulse B_R is produced during a scan of a row of characters only if the reference mark 46 is intercepted by aperture 22b. It will be noted that because the one-shot T1 remains true only for a predetermined time during which the reference mark is expected, other pulses produced by the signal B at other times will not be confused as the reference mark 46.

Having explained how the pulse B_R is derived, which represents the situation where aperture 22b intercepts the reference mark 46 during a scan, it will now be explained how the signal B_R' is derived, which represents the situation where aperture 22b fails to intercept the reference mark 46. Referring again to FIG. 3, it will be seen that the derived signal B_R is fed to the false input on₁ of flip-flop N1, which is switched to the true state at the start of each scan by the pulse S. Thus, as shown in waveform B_R and N1 of FIGS. 5 and 6, if the reference mark is intercepted by aperture 22b (FIG. 5 situation), the pulse B_R is produced and flip-flop N1 is switched back to its false state. The signal B_R' is now derived by feeding the true output N₁ to an "AND" gate 54 along with the false output T₁' of the one-shot T1. Then, as shown in the waveforms of FIG. 5, if the pulse B_R appears, N₁ will be switched false before T₁' becomes true and the signal B_R', which is the output of "AND" gate 54, will thus remain false during the scan. However, as shown by the waveforms in FIG. 6, if the pulse B_R does not appear because the aperture 22b does not intercept the reference mark 46, flip-flop N1 will not be switched false and will thereby be true when the one-shot T1 returns

to its false state, causing T_1' to become true. When this occurs, the output signal B_R' of "AND" gate 54 will also become true (since both N_1' and T_1' will be true) and, as shown by waveform B_R' in FIG. 6, will remain true until T_1' again becomes false when the pulse S produced at the start of the next scan switches T_1 to the true state.

The signals B_R and B_R' derived as just described are fed, along with the false outputs N_1' and T_1' of flip-flop N_1 and one-shot T_1 , respectively, and the signals A , B , C , D , and S obtained from detector circuitry 32, to a character recognition unit 250 which contains the recognition, recording and outputting means of the character reading system. The character recognition unit 250 is constructed and arranged for operation in response to these signals applied thereto to recognize each character in the row being scanned, to provide for error detection and re-scanning of a row in response to a detected error, to store the character recognition information for each character until all the characters in the row have been read, and then to output each row of characters to suitable output equipment 252 in a manner determined by the character in the row adjacent the reference mark 46.

Besides providing for character read-out, the character recognition unit 250 also provides an output signal E_8 whenever a row has been re-scanned eight times, in response to a detected error in the row, without being able to properly read the row. The signal E_8 is coupled to an error mark unit 18 disposed adjacent the scanning station 17 and constructed and arranged to mark the tape 12 adjacent the row containing the unreadable error in response to the signal E_8 becoming true.

The character recognition unit 250 additionally provides true and false output signals H_1 , H_1' , Q_1 , and Q_1' from flip-flops H_1 and Q_1 in the unit 250 to control the operation of the synchronous motors 13 and 40. At this time, it will be sufficient to note that flip-flop H_1 becomes true during character read-out to permit motors 13 and 40 to be halted during the read-out period, while flip-flop Q_1 becomes true when an error is detected in a row, causing motor 13 to reverse and back up tape 12 for a re-scan of the row containing the error. The inertia of the motor 13 and the inherent sloppiness of the tape transport 14 (FIG. 3) results in an essentially random back-up of tape 12 which provides, with a high degree of probability, that each re-scan of a row will be randomly different. While a randomly different back-up of tape 12 is conveniently provided in this manner, it will be understood by those skilled in the art that other suitable means may also be provided for this purpose.

Referring now to FIG. 7, a detailed block and circuit diagram is illustrated of the character recognition unit 250 shown in block form in FIG. 3. Before considering the circuitry of FIG. 7, however, it will be helpful to first provide a functional description of the operations which the character recognition unit 250 is to perform in accordance with the invention. These are listed below as follows:

(1) Operation of the recognition circuitry of unit 250 is initiated when the aperture 22b first intercepts a reference mark which, as described in connection with FIGS. 3, 5, and 6, may be determined by the appearance of the pulse B_R .

(2) Each character in the row has a "read" scan performed thereon when the fourth aperture 22d first fails to intercept any portion of the character, thereby insuring correct vertical registration.

(3) After aperture 22b intercepts the reference mark of a row of characters, horizontal registration and column identification are achieved by cycling a program counter 80 through a predetermined number of counts each time any one of the four apertures 22a, 22b, 22c, or 22d intercepts the vertical segment provided in zone U for each character. The position of each character in the row is then located by a column counter 105 which counts

the number of times the program counter 80 is cycled. The use of four apertures instead of only the two required for scanning the paths r_t and r_b (FIG. 1) assures that there will be no error in the column count since at least one aperture will always intercept the vertical segment provided in zone U of each character for a wide range of vertical misregistration.

(4) After the aperture 22b first intercepts the reference mark adjacent a row of characters, character information is detected for every scan as the row is progressively scanned. Some or all of this information is recorded for error detection as will be described later on. However, the character information detected is not used for recognition; that is, no "read" scan is performed on a character until the aperture 22d first fails to intercept any portion of the character. Character information is also used for recognition of a character if a "read" scan was previously performed thereon.

(5) After all eight characters in the row have been read and recorded for outputting, there is no further detecting of character information and scanning continues until the aperture 22b first misses the reference mark, indicating that the row has been scanned. This indication is conveniently provided by the signal B_R' becoming true, as described in connection with FIG. 3. At such a time, the flip-flop H_1 is switched to the "true" state halting the synchronous motors 13 and 40 (FIG. 3) and all eight characters of the row which have been recorded are now outputted in a manner determined by the character adjacent the reference mark. After all eight characters have been outputted, flip-flop H_1 is switched back to the false state and scanning proceeds to the next row. It should be apparent that the stopping of motors 13 and 40 will be unnecessary when the outputting does not require more time than required to begin the scanning operations of the next row of characters.

(6) In the event that in performing a "read" scan on one of the characters in the row, the character information detected is recognized as an error, or if eight columns are not counted in the row, an error signal is generated to switch flip-flop Q_1 to the true state, as a result of which, synchronous motor 13 (FIG. 3) reverses to cause the tape 12 to back-up. During the reversal of the movement of the tape 12, the scanning continues and the first time that the top of the reference mark is not intercepted by the second aperture 22b, which may again be recognized by the signal B_R' becoming true, the flip-flop Q_1 is switched back to the false state and a different re-scan is thereby performed on the row containing the error. This error detection and re-scanning is permitted to occur eight times and, if an error is again detected during the following re-scan, the signal E_8 becomes true to cause the error mark unit 18 in FIG. 3 to mark tape 12 adjacent the mis-read row. Scanning then progresses just as if all eight characters on the row had been correctly read and, when aperture 22b first misses the bottom of the reference mark to indicate that the row has been scanned (that is, B_R' becomes true), flip-flop H_1 is again switched to the true state. However, instead of outputting each row of characters as would be done if all eight characters were correctly read, an error code is outputted to indicate that the row could not be read, after which flip-flop H_1 is switched back to the false state and scanning proceeds to the next row.

With the above functional description in mind, the construction and operation of the character recognition unit 250 shown in FIG. 7 will now be described. Signals A , B , C , and D , which are obtained from detector circuitry 32 in FIG. 3, are fed to one input of "AND" gates 62, 64, 66, and 68, respectively. The other input of each of these "AND" gates 62, 64, 66, and 68 is fed by the output 70a of another "AND" gate 70, which is in turn fed by the signals N_1' , T_1' , E_8' , J_8' , and Q_1' to form the logical product thereof. It will be remembered from FIGS. 3, 5, and 6 that signals N_1' and T_1' fed to "AND" gate

70 are the false outputs of flip-flop N1 and the one-shot T1, respectively, the signal N1' being true only after a reference mark has been intersected by aperture 22b, and the signal T1' being true only after the maximum time has elapsed for which the reference mark is permitted to occur after the apertures leave the shroud 24. As mentioned previously, the signal Q1' fed to "AND" gate 70 is the false output of flip-flop Q1, while the signal E8' fed to "AND" gate 70 is the inverse of the signal E8 generated when eight re-scans have failed to read a row correctly. Finally, the signal J8' fed to "AND" gate 70 is the inverse of the signal J8 generated when all eight characters on a row have been read. Since the output 70a of "AND" gate 70 is true only when all of the above described inputs thereto are true, "AND" gates 62, 64, 66, and 68 are enabled to pass the pulses of signals A, B, C, and D only after the reference mark is detected by aperture 22b and only when the error flip-flop Q1 has not been switched true and the error signal E8 or the final character signal J8 is not present. By so restricting the feeding of signals A, B, C, and D to the remainder of the character recognition unit 250, the pulses produced by these signals A, B, C, and D during periods when they are not required are conveniently eliminated and prevented from interfering with system operation. To distinguish the outputs of "AND" gates 62, 64, 66, and 68 from the signals A, B, C, and D they are designated as A1, B1, C1, and D1, respectively.

The manner in which the signals A1, B1, C1, and D1 are used to uniquely determine the position of the zones U, V, W, X, and Y for each character will now be explained. Still referring to FIG. 7, it will be seen that the signals A1, B1, C1, and D1 are fed to an "OR" gate 72 whose output is in turn fed to a delay network 73 providing a delay t_D , and then to the set input g_1 of a flip-flop G1. Thus, in the normal scanning of a row of characters (assuming that the reference mark has been detected by aperture 22b), flip-flop G1 will be switched to the true state t_D microseconds after the first pulse produced by any one of the signals A1, B1, C1, or D1, in response to its respective aperture 22a, 22b, 22c, or 22d intercepting the vertical segment provided in zone U for each character. When flip-flop G1 is switched true, its true output G1, which is fed to the "start" input of a program clock 75, also becomes true, causing clock 75 to generate clock pulses at a predetermined rate determined in accordance with system requirements. These clock pulses are fed to the "advance" input of a program counter 80 which is constructed and arranged to count, in response to each clock pulse, from an initial program count P_0 up to the program count P_{15} and then, on the next clock pulse following, to return to the initial program count P_0 . The repetition rate of the clock pulses provided by program clock 75 is chosen so that, when program counter 80 returns to program count P_0 , apertures 22a, 22b, 22c, and 22d will have scanned past the first character.

Since the initial program count P_0 of program counter 80 is fed to the reset input g_1 of flip-flop G1 through "AND" gate 74, the other input of which is the true output G1 of flip-flop G1, when the program counter 80 returns to its initial program count P_0 on the sixteenth clock pulse, flip-flop G1 will be switched back to its false state. When this occurs, the false output G1' of flip-flop G1, which is connected to the "stop" input of program clock 75, will become true to stop clock 75 and thereby cause program counter 80 to remain at its initial program count P_0 where it first started until one of the apertures 22a, 22b, 22c, or 22d next intercepts the vertical segment in zone U of the next adjacent character in the row.

In summary, therefore, the first one of the signals A1, B1, C1, or D1 which intercepts the vertical segment provided in zone U for each character (after the reference mark has been detected by aperture 22b), causes flip-flop G1 to become true t_D microseconds later to start

program clock 75 and cause program counter 80 to count through program counts P_0 to P_{15} , starting and ending with the initial program count P_0 , at which time the apertures 22a, 22b, 22c, and 22d will have scanned past the character. The program count P_0 is fed to the reset input g_1 through gate 74 along with the true output G1 of flip-flop G1, instead of directly, in order to prevent program count P_0 in which program counter 80 rests, from interfering with flip-flop G1 being switched true when one of the apertures 22a, 22b, 22c, and 22d intercepts the vertical segment in zone U of the next character.

The relation of each character to program counts P_0 to P_{15} provided by program counter 80 in the manner just described, will be better understood with reference to FIG. 8, which is an enlarged view of the stylized character "2" showing the position of each program count with respect thereto. It will be remembered from the discussion of the previous paragraph that the first one of the apertures 22a, 22b, 22c, or 22d which intercepts the vertical segment provided in zone U for each character causes flip-flop G1, after a delay t_D , to be switched true to start program clock 75 and thereby cycle program counter 80 from its initial program count P_0 to program count P_{15} and then back again to P_0 . For the positioning of the apertures 22a, 22b, 22c, and 22d with respect to the numeral "2" shown in FIG. 8, it will be seen that the aperture 22b is the one which will first intercept the vertical segment 2a provided in zone U for the character "2" to cause a pulse to be produced by the corresponding signal B1.

As was brought out previously, each pulse produced by signals A1, B1, C1, and D1, in response to the interception of a vertical character segment by a respective aperture, occurs substantially at the center line of the vertical segment. Thus, it can accurately be presumed that the pulse produced by signal B1 in response to aperture 22c traversing the vertical segment 2a of character "2" in FIG. 8 occurs substantially at the center line 2b, which is also the center of zone U. Consequently, with three program counts being provided for each of the zones V, W, X, and Y, as shown in FIG. 8, only the equivalent of one and one-half program counts is required for the remaining half of zone U in order to achieve correct horizontal registration, that is, correct positioning of the zones U, V, W, X, and Y with respect to each character. These remaining one and one-half program counts needed for zone U are obtained by choosing the delay t_D provided by delay network 73, so that program count P_1 produced by program counter 80 in response to the first clock pulse, is present during the last one-third of zone U, as illustrated in FIG. 8. The program counts P_2 to P_4 , P_5 to P_7 , P_8 to P_{10} and P_{11} to P_{13} , will then accurately define zones V, W, X, and Y, respectively.

As was mentioned previously, each of the characters in the system is stylized to have at least one vertical segment in zone U. Thus, accurate horizontal positioning of the zones U, V, W, X, and Y for every other character in the system may be achieved in the same manner as explained with respect to the character "2" illustrated in FIG. 8. It may additionally be noted at this time that, since horizontal registration is determined in response to the detection of the center line of the vertical segment which is provided in zone U for each character (and is thus also the center line of zone U), the horizontal location of all vertical segments of a character need be controlled only with respect to the centers of their vertical segments, without regard to printing weight or segment width. This makes possible greatly reduced tolerances in character printing quality as well as in character dimensioning.

In addition to the program counts P_2 to P_{13} which are required for zones V, W, X, and Y, it will be noted in FIG. 8 that program counts P_{14} and P_{15} are also provided. These program counts P_{14} and P_{15} provide intervals for converting the ten-digit number formed from

two five-digit binary numbers detected for each character during a "read" scan into a single five-digit number, and for permitting recording and/or error detection where appropriate, as will be explained in more detail further on in the description of FIG. 7. It will also be noted from FIGS. 7 and 8 that zone program counts P_U , P_V , P_W , P_X , and P_Y are provided by program counter 80 for each of the zones U, V, W, X, and Y respectively corresponding thereto, each zone program count being present during the time for which its respective zone is being scanned by apertures 22a, 22b, 22c, and 22d.

An additional point to recognize at this time is that sufficient spacing between characters should, of course, be provided to permit program counter 80 to return to its initial count P_0 before the vertical segment in zone U of the next adjacent character is encountered by any of the apertures 22a, 22b, 22c, or 22d. During the scanning of a row, therefore, program counter 80 will be cycled in response to each character in the row and, as a result of such cycling, will provide accurate horizontal registration for each character (as described for the character "2" in FIG. 8), regardless of the horizontal spacing between characters, as long as the spacing provided is greater than the minimum required to permit program counter 80 to return to its initial count P_0 before the next character is intercepted. Thus, horizontal misregistration, such as illustrated between characters "3" and "9" of row 48 in FIG. 2, can readily be handled without error.

Returning now to FIG. 7, it will be seen that signal B_1 , corresponding to aperture 22b, is fed to one input of each of a first group of five "AND" gates 82, 84, 86, 88, and 90, while signal C_1 corresponding to aperture 22c is fed to one input of each of a second group of "AND" gates 92, 94, 96, 98, and 100. The other inputs of these two groups of "AND" gates are fed by respective ones of the program zone counts P_U , P_V , P_W , P_X , and P_Y , as shown, program zone count P_U being fed to "AND" gates 82 and 92, program zone count P_V being fed to "AND" gates 84 and 94, program zone count P_W being fed to "AND" gates 86 and 96, program zone count P_X being fed to "AND" gates 88 and 98, and program zone count P_Y being fed to gates 90 and 100.

The outputs of "AND" gates 82, 84, 86, 88, and 90 are fed to respective ones of the set inputs f_1 , f_2 , f_3 , f_4 , and f_5 of flip-flops F1, F2, F3, F4, and F5, while the outputs of "AND" gates 92, 94, 96, 98, and 100 are fed to respective ones of the set inputs f_6 , f_7 , f_8 , f_9 , and f_{10} of flip-flops F6, F7, F8, F9, and F10. Consequently, in scanning a character, such as the character "2" illustrated in FIG. 8, flip-flops F1, F2, F3, F4, and F5 will be set in accordance with the presence or absence of character segments in each of the zones U, V, W, X, and Y, respectively, traversed by the aperture 22b, while flip-flops F6, F7, F8, F9, and F10 will be set in accordance with the presence or absence of character segments in each of the zones U, V, W, X, and Y, respectively, traversed by the aperture 22c. If a binary "1" indicates the presence of a vertical character segment and a binary "0" indicates the absence of a vertical character segment then, for the character "2" shown in FIG. 8, flip-flops F1, F2, F3, F4, and F5 would have the settings 10000, respectively, while F6, F7, F8, F9, and F10 would have the settings 00001, respectively. These binary codes correspond to the codes of character "2" as shown in FIG. 1. It will be noted that flip-flops F1 to F10 are all caused to be re-set to their "0" settings by program count P_0 applied to the reset inputs of f_1 to f_5 and f_6 to f_{10} thereof, in order to prepare them for receiving character information.

As each character in a row is scanned, therefore, flip-flops F1 to F10 will be set up in accordance with the presence or absence of character segments traversed by apertures 22b and 22c in each of the zones U, V, W, X, and Y. It next becomes necessary to provide means for determining the position of each character in the row.

This position information is obtained by means of a column counter 105 (located in the lower portion of FIG. 7) which is caused to advance one count, in consecutive numerical order, each time a character is scanned, by feeding the program count P_1 to the "advance" (Y) input of column counter 105 through an "OR" gate 107. The particular advance input fed by P_1 through "OR" gate 107 is indicated as the (Y) input, which provides for counting in consecutive numerical order. Also provided are "advance" inputs ($\neg \square$) and (P), the purpose of which will be described further on in this specification.

In order to insure that the column counter 105 is initially at zero at the start of a scan of a row, the reference pulse B_R is fed to the "reset" input of the column counter 105 through another "OR" gate 109 (along with signals E_8 and J_8) to reset column counter 105 to its zero count K_0 . Consequently, since program counter 80 then cycles once for each character in the row, as a result of which, program count P_1 advances column counter 105 one count for each character scanned, the count of the column counter 105 will correspond to the position in the row of the character being scanned. The use of the four spaced apertures 22a, 22b, 22c, and 22d assures that, for each scan in which the reference mark is intercepted by aperture 22b, at least one of the four apertures will intercept the vertical segment provided in zone U for each character in the row, even in the presence of appreciable misregistration between adjacent characters, such as illustrated occurring between the characters "7" and "1" in row 48 of FIG. 2. As a result, program counter 80 will reliably cycle for each character in the row and the count of column counter 105 will always correctly identify the position in the row of the character being scanned.

Referring again to FIG. 8, it will be seen that after the count P_{13} , which is the last count of zone Y, program counter 80 counts through P_{14} and P_{15} before returning to its initial count P_0 . Considering count P_{14} first, if a "read" scan has been performed on the character scanned (that is, if apertures 22b and 22c have substantially traversed paths r_t and r_b illustrated in FIG. 1), the two five-digit binary numbers set up in flip-flops F1 to F5 and F6 to F10 during zone counts P_U , P_V , P_W , P_X , and P_Y are converted by a code converter 110, during count P_{14} , into a single five-digit number representative of the character scanned. It will be remembered that the stylizing is chosen so that two reading errors are required in order to mis-identify a character. As a result, a single five-digit code can be derived from the two five-digit binary numbers obtained for each character which will be sufficient to represent all the characters in the system. The code converter 110 to which the true outputs F_1 to F_5 and F_6 to F_{10} of flip-flops F1 to F5 and F6 to F10 are fed is provided for this purpose. By performing this conversion before operating further on the character information makes possible a considerable reduction in circuit complexity, since the data to be processed is reduced by one-half. Code converters, such as the ten-to-five code converter 110 illustrated in FIG. 7, may readily be provided by those skilled in the art.

As noted in the previous paragraph, code converter 110 is caused to operate to convert the character information set up in flip-flops F1 to F5 and F6 to F10, if the character is in a "read" scan position with respect to the apertures 22b and 22c, which are spaced in accordance with the spacing of r_t and r_b in FIG. 1. However, from the time that aperture 22b first detects a reference mark, apertures 22b and 22c will continuously intercept character information for each character during the progressive scanning of a row and cause flip-flops F1 to F10 to be set up in accordance therewith, even though the information detected will not be meaningful until the character is properly aligned for a "read" scan. In order to ignore the settings of flip-flops F1 to F10 until a "read" scan is performed on a character, code converter 110 is permitted to convert the settings of flip-flops F1

to F₁₀ only in response to an energization signal 119a, which is caused to occur at P₁₄ only if a "read" scan has been performed on the character scanned. By so controlling the operation of code converter 110, if no conversion takes place at P₁₄, the return of program counter 80 to its initial program count P₀ will conveniently discard the meaningless information in flip-flops F1 to F₁₀ by resetting these flip-flops to the "0" state in preparation for scanning the next character in the row.

Aperture 22d provides a most advantageous way of determining whether or not apertures 22b and 22c are properly positioned for a "read" scan (along paths r_t and r_b) of a character, in order to determine when code converter 110 is to be permitted to operate. This is accomplished by spacing aperture 22d with respect to apertures 22b and 22c so that apertures 22b and 22c will have substantially the correct alignment for a "read" scan of a character during the scan that aperture 22d completely misses the character for the first time. This condition is typically illustrated in FIG. 8. It has been found that by using this condition to determine when a "read" scan has been performed, significantly greater tolerances on character dimensions are possible, as compared to other approaches to vertical registration, for example, the counting of the number of times a character portion is detected. It is important to note that since aperture 22d is to be used for this purpose, it is necessary that the corresponding signal D₁ provide a pulse not only when a vertical segment is intercepted by aperture 22d, but also, when any portion of a character is intercepted thereby, such as the horizontal portion 2d of the character "2" illustrated in FIG. 8. For this reason, the detector circuitry 32 illustrated in FIGS. 3 and 4 is designed so that a pulse is produced by signal D₁ when any portion of a character is detected. As will be understood by those skilled in the art, suitable means for this purpose may readily be provided in detector circuitry 32.

As mentioned previously, in order to control whether or not code converter 110 is to convert at program count P₁₄, code converter 110 is energized only in response to the energization signal 119a. This energization signal 119a is provided when the output of an "AND" gate 119 becomes true. Program count P₁₄ is fed to "AND" gate 119 along with the false output E₁' of a flip-flop E1 and the false output L₁' of a flip-flop L1, as shown in FIG. 7. Since signal D₁ corresponding to aperture 22d is fed to the set input e₁ of flip-flop E1 if, during the scan of the character, a pulse is produced by signal D₁ in response to aperture 22d intercepting a portion of the character, flip-flop E1 will be switched to its true state. As a result E₁' will become false, inhibiting "AND" gate 119 and thereby preventing operation of code converter 110. On the other hand, if aperture 22d fails to intercept any portion of the character scanned, so that no pulse is produced by signal D₁, then flip-flop E1 will remain in its false state and its false output E₁' will remain true. Thus, if L₁' is also true (which is the case if this is the first time aperture 22d has failed to intercept any portion of the character scanned, as will hereinafter be described in detail), a "read" scan is indicated and program count P₁₄ will pass through "AND" gate 119 to provide the energization signal 119a. Code converter 110 will then convert the ten-digit binary number provided by the outputs F₁ to F₁₀ into a single five-digit binary number representative of the character scanned.

The digits of the five-digit binary number thus provided by code converter 110 at program count P₁₄, in response to a "read" scan, are fed through respective "OR" gates 112, 114, 116, 118, and 120 to be set up in respective ones of flip-flops M1 to M5. Then, at program count P₁₅, the outputs of flip-flops M1 to M5 are applied through respective "AND" gates 122, 124, 126, 128, and 130 to respective row drive lines 129 of a memory core array 200. Program count P₁₅ effectively opens "AND" gates 122, 124, 126, 128, and 130, since "AND" gate 125,

whose output 125a feeds the other input of each of "AND" gates 122, 124, 126, 128, and 130, is in turn fed by program count P₁₅ and the false outputs Q₁' and H₁' of flip-flops Q1 and H1, which false outputs Q₁' and H₁' are normally true. Flip-flops M1 to M5 are constructed and arranged so that each flip-flop which is set to the "1" state will cause, at program count P₁₅, one-half write select current to be applied to the row drive line 129 of the row of cores of the memory core array 200 corresponding thereto, while each flip-flop which is set to the "0" state will apply no current to the write drive line 129 of its corresponding row of cores.

Memory core array 200 is comprised of eight columns of cores, each column having five cores. The eight columns of cores respectively correspond to the eight characters in each row on the tape 12 (FIG. 2), and the five cores in each column provide for the storage of a five-digit binary number representative of a respectively positioned character on the row after a "read" scan has been performed thereon. At program count P₁₅, in addition to the one-half write select current being applied to those rows of cores whose corresponding M1 to M5 flip-flops are set to the "1" state (as described in the previous paragraph), a particular column of cores in array 200, corresponding to the count of column counter 105 (which in turn corresponds to the position of the character in the row), also receives half-select write current applied thereto. If, for example, column counter 105 is at count K₂, the second column of cores in array 200 will receive one-half write select current at P₁₅, causing those cores in the second column which also receive one-half write current from a corresponding M1 to M5 flip-flop to receive a total of full write select current to switch these cores from the "0" to the "1" state, the other cores in the second column as well as all the other cores in the array 200 receiving no greater than one-half write select current and thereby remaining essentially undisturbed.

It will thus be understood that the five-digit binary number set up in flip-flop M1 to M5 by code converter 110 during program count P₁₄, in response to a "read" scan performed on the character scanned, will thereby be transferred, during program count P₁₅, to the column of cores in array 200 corresponding to the position of the scanned character in the row. In a similar manner, the five-digit binary number corresponding to every other character in the row, which is likewise set up in flip-flops M1 to M5 as a result of a "read" scan being performed thereon, is recorded in a respective column of cores in array 200 corresponding to the position of the character in the row.

The specific manner in which half-select write current is applied to the column of cores of memory core array 200 in accordance with the count of column counter 105 will now be explained in detail. Each of the outputs K₀, K₁, K₂, etc., of column counter 105, when true, is a positive signal which, when inverted by its respective inverter I and fed through a base resistor to the base of its respective normally cut off transistor 137, causes transistor 137 to turn on and thereby effectively ground, through the grounded transistor emitter, the write and read column drive lines 133 and 135 connected to the transistor collector. The write column drive line 133 passing through each column of cores is the only one that need be considered at this time, and it will be seen that the opposite end of each write column drive line 133 is fed through a respective diode 131 to the emitter of a normally cut-off write transistor 141. The collector of transistor 141 is connected to a D.C. voltage -V₁ through a collector resistor 142, and the base of transistor 141 is connected through a base resistor and an inverter I to the output 140a of an "AND" gate 140. When program count P₁₅ appears, it passes through "AND" gate 140 (since Q₁' and H₁' also fed to "AND" gate 140 are normally true) to turn on transistor 141 and thereby cause a current to flow in the column drive line 133 whose transistor 137 has been turned on by the count of column counter 105. The

value of $-V_1$ and collector resistor 142 is chosen so that the current flowing in the selected column drive line 133 is equal to one-half the write select current required to switch a core in array 200 from the "0" to the "1" state and, when added to the additional one-half write select current applied to those cores of the selected column whose M1 to M5 flip-flops are set to the "1" state, causes the settings of flip-flops M1 to M5 to be transferred, at program count P₁₅, to the column of cores in array 200 corresponding to the position in the row of the character scanned.

It should now be evident just how the five-digit binary number provided at the output of code converter 110 at program count P₁₄, in response to a "read" scan performed on the character scanned, is set up in flip-flops M1 to M5 and then, at program count P₁₅, recorded in a column of the memory core array 200 corresponding to the position of the character in the row. With this explanation as background, the purpose of flip-flop L1, whose false output L₁' also determines whether or not the code converter 110 will operate at program count P₁₄, will now be understood as follows. It will be appreciated that once a particular character has a "read" scan performed thereon and an identifying five-digit binary number recorded in a respective column of cores of memory core array 200, aperture 22d will still fail to intercept any portion of a character as scanning progresses. Thus, the false output E₁' of flip-flop E1 will remain true and, if no other provision were available, would cause code converter 110 to operate, even though apertures 22b and 22c would no longer traverse the paths r_t and r_b corresponding to a "read" scan. As mentioned previously, aperture 22d indicates a "read" scan only when it first fails to intercept a portion of the character scanned. Thus, to prevent upsetting a properly recorded five-digit binary number in memory core array 200, it is necessary to determine whether or not a "read" scan has already been performed on a particular character, in which case, a five-digit binary number is already recorded in the respective column of array 200; if so, the code converter 110 should be prevented from operating, since apertures 22b and 22c will no longer be in the correct position for a "read" scan. To accomplish this, it has been found convenient during an early program count in the cycling of program counter 80 such as P₅, to read out the five-digit binary number recorded in the column corresponding to the position of the character in the row.

Since column counter 105 has already been set, at program count P₁, to a count corresponding to the character being scanned, read-out from the five cores in the corresponding column in array 200 is conveniently accomplished by applying program count P₅ through "OR" gate 150 and an inverter I to turn on a normally cut off read-transistor 151, whose collector is connected to a D.-C. voltage $-V_2$ through collector resistor 152, and whose emitter is connected to each read column drive line 135 through a respective diode 139. At program count P₅, therefore, current will flow through the read column drive line 135 whose respective transistor 137 has been turned on by column counter 105, the value of $-V_2$ and the collector resistor 152 being chosen so that the current flowing in the selected read column drive line 135 is equal to full read select current. Thus, if any of the cores in the selected column are in the "1" state, the full read select current flowing therethrough causes these cores to be switched of the "0" state, as a result of which, a pulse is induced in each row sense line 143 corresponding thereto. Each such induced pulse is then amplified by respective sense amplifiers 163 to provide signals S₁, S₂, S₃, S₄, and S₅ which correspond to the five-digit number read out of the five cores in the selected column, the presence of a pulse designating a binary "1" and the absence of a pulse designating a binary "0." These signals S₁, S₂, S₃, S₄, and S₅ are then fed through respective "AND" gates 172, 174, 176, 178, and 180 (since H₁' fed through "OR" gate 181 to the other input

of each of these "AND" gates is normally true) and respective "OR" gates 112, 114, 116, 118, and 120 to set up respective ones of the flip-flops M1, M2, M3, M4, and M5 in accordance therewith.

In summary, therefore, it will be understood that at program count P₅, the data stored in the column of cores in array 200, corresponding to the position in the row of the character being scanned, is read out of array 200 and set up in respective ones of flip-flops M1 to M5. It will be noted that program count P₁ is fed through "OR" gate 199 to the reset inputs $_{0m_1}$ to $_{0m_5}$ of flip-flops M1 to M5 in order to clear these flip-flops preparatory to their being set up at program count P₅, in accordance with the data stored in the selected column of cores in array 200.

Now referring specifically to flip-flop L1, it will be seen that, at program count P₇, the true outputs M₁, M₂, M₃, M₄, and M₅ are each fed to an "OR" gate 179, the output of which is fed to an "AND" gate 181 along with program count P₇, the output of "AND" gate 181 being in turn fed to the set input l_1 of flip-flop L1. Thus, if any of the flip-flops M1 to M5 were set in the "1" state at program count P₅, in response to a "1" being recorded in a respective core of the column of cores selected by column counter 105, then flip-flop L1 will be switched to the true state at program count P₇. This occurs because, if any of the outputs M₁ to M₅ are true, "AND" gate 181 will be enabled to permit program count P₇ to pass therethrough and be applied to set input l_1 to switch flip-flop L1 to the true state, output L₁' of flip-flop L1 then becoming false.

It will be understood, therefore, that if a "1" is recorded in any core of the column of cores in array 200, corresponding to the position in the row of the character being scanned, L₁' will become false in the manner described in the previous paragraph. Since a "1" can be placed in a core of a column in array 200 only if a five-digit binary number corresponding to a character is recorded therein (there being no such character in the system whose five-digit binary number consists of five binary zeros), then the fact that L₁' is false at P₁₄ will indicate that the particular character being scanned has already been read and recorded in its respective column. With L₁' then false, program count P₁₄ is prevented from passing through "AND" gate 119 and energization signal 119a will not appear to energize code converter 110, even though E₁' is true as a result of aperture 22d failing to intercept any portion of the character scanned.

If, however, outputs M₁, M₂, M₃, M₄, and M₅ are all zero at program count P₇, indicating that the character has not been recorded in its respective column in array 200, then flip-flop L1, which is reset to the false state at program count P₀ will remain false and L₁' will be true at program count P₁₄ to permit code converter 110 to be operated if, of course, E₁' is also true, indicating that aperture 22d has failed to intercept any portion of the character scanned. Consequently, code converter 110 can operate at program count P₁₄ only if the two conditions of a "read" scan are both present; that is, (1) if aperture 22d has failed to intercept any portion of the character scanned so that E₁' is true at P₁₄ and (2) if the character has not been already read and recorded in its respective column of array 200 so that L₁' is also true at P₁₄. Or, stated another way, a "read" scan has occurred if this is the first time aperture 22d has failed to intercept any portion of the character scanned.

Returning temporarily to a consideration of memory core array 200 once more, it will be remembered that, at program count P₅, the column of cores corresponding to the position in the row of the character being scanned was read out and set up in flip-flops M1 to M5. All of the cores in the selected column will thus now be in the "0" state because of the destructive read-out inherent in a magnetic core memory. Consequently, if the column of cores read out of array 200 at program count

P_5 stored a five-digit number corresponding to a recorded character, it is necessary that this five-digit number be written back into the selected column, or it will be lost. Fortunately, this may readily be accomplished in the character recognition unit 250 of FIG. 7, since the five-digit binary number set up in flip-flops M1 to M5 at program count P_5 will still be present at program count P_{15} because code converter 110 will not have operated. Thus, at program count P_{15} , the five-digit binary number represented by the settings of flip-flops M1 to M5 will automatically be returned to its respective column of cores in array 200, just as if a new five-digit number corresponding to a character was just being recorded in its respective column.

In summary, therefore, it will be understood that the settings of flip-flops M1 to M5 are always transferred at program count P_5 (unless either or both Q_1' or H_1' is false) to the column of cores selected by column counter 105. If the character being scanned has already been read and recorded in its respective column, then the five-digit number already recorded in the cores of the respective column is set up in flip-flops M1 to M5 at program count P_5 and remains undisturbed at program count P_{14} when code converter 110 does not operate, whereupon, at program count P_{15} , the five-digit number in flip-flops M1 to M5 is again transferred back to its respective column.

If, however, no five-digit number is stored in the respective column of the character being scanned so that all "0's" are set up in flip-flops M1 to M5 at program count P_5 , causing L_1' to be true at program count P_7 , two situations are then possible. First, if aperture 22d has failed to intercept any portion of the character scanned and E_1' is thereby set true along with L_1' to indicate a "read" scan was performed then, at program count P_{14} , flip-flops M1 to M5 will be set by code converter 110 to the five-digit binary number corresponding to the character scanned. At program count P_{15} , this five-digit binary number will then be transferred to the column of cores in array 200 corresponding to the position of the character in the row. The second situation occurs if aperture 22d has intercepted a portion of the character scanned so that E_1' is set false even though L_1' is true, thereby indicating that a "read" scan was not performed. Code converter 110 will then not operate at program count P_{14} and flip-flops M1 to M5 will remain set to all "0's" so that, at program count P_{15} , the same "0" settings read out of the selected column of cores in array 200 are written back into the selected column, and the column will continue to indicate that no character is recorded therein.

Now that the means for reading and recording a typical character in array 200 have been explained, the manner in which outputting of a row of characters is achieved after all eight characters in the row have been read and recorded will be understood from the following further description of the character recognition unit 250. Referring again to code converter 110, it will be seen that, in addition to providing a five-digit binary output to flip-flops M1 to M5 at program count P_{14} in response to a "read" scan, code converter 110 also provides a code correct signal V_c , which is obtained in response to energization signal 119a of "AND" gate 119 and the outputs F₁ to F₁₀ of flip-flops F₁ to F₁₀. When present, at program count P_{14} , code correct signal V_c indicates that a valid ten-digit binary number was obtained in response to the "read" scan performed on the character scanned, that is, that the combination of the outputs F₁ to F₁₀ provided by the "read" scan is a valid character combination. It will be appreciated by those skilled in the art that code correct signal V_c can readily be provided by suitably combining signals 119a and F₁ to F₁₀ by means of well-known logical circuitry, such as illustrated in the typical embodiment of code converter 110 in FIG. 9.

Since code correct signal V_c occurs only when a "read" scan has been performed on a character and a valid character combination set up in flip-flops F₁ to F₁₀, the signal V_c may conveniently be fed to the "advance" input of a character counter 210 to permit a count to be maintained of the number of characters on the row which have had a proper "read" scan performed thereon and, thus, have been recorded in respective columns of memory core array 200. When character counter 210 reaches its eighth count, a positive (true) signal J_8 is produced to indicate that all eight characters on the row have been properly read and recorded and that the row is now ready for outputting. The signal J_8 is fed through an "OR" gate 123 to one input of an "AND" gate 126, which is in turn fed to the set input h_1 of flip-flop H₁, the other input of "AND" gate 126 being fed by the signal B_R' , which is derived as explained in connection with FIG. 3.

As shown in FIG. 5, the signal B_R' will not be true while aperture 22b continues to intercept the reference mark 46 during progressive scanning of the row. Thus, the output of "AND" gate 126 will remain false until scanning of the row progresses to a point where aperture 22b finally fails to intercept the reference mark, for example, as shown in FIG. 6. For the scan for which this occurs, B_R' becomes true and since J_8 is also true, the output of "AND" gate 126 becomes true to switch flip-flop H₁ to the true state. As a result, true output H₁ of flip-flop H₁ becomes true while false output H_{1'} becomes false, which initiates the operation of output clock 215 and, at the same time, stops both synchronous motors 13 and 40 to halt further scanning.

Also, as a result of flip-flop H₁ being switched true, character counter 210 is reset to zero by true output H₁, read transistor 151 associated with memory core array 200 is turned on by true output H₁, and gates 125 and 140 are inhibited by output H_{1'} becoming false to prevent the data in columns in memory array 200 from being disturbed by extraneous signals during outputting. Further, as a result of character counter signal J_8 having appeared, column counter 105 is reset to zero and "AND" gate 70 is inhibited, which in turn inhibits "AND" gates 62, 64, 66, and 68, to prevent unwanted pulses from appearing in signals A₁, B₁, C₁, and D₁ once signal J_8 appears. In addition, when signal B_R' becomes true, flip-flop N1 (FIGS. 3 and 6) remains true, since there will be no reference mark signal B_R to switch it false; thus, N_{1'} becomes false to continue to effectively inhibit "AND" gate 70 after H₁ resets character counter 210 to zero. Thus, as a result of character counter 210 reaching J_8 and flip-flop H₁ thereby being switched true, scanning is halted, possible interfering signals are eliminated and preparation is made to output the eight characters recorded in the eight columns of memory core array 200.

When output clock 215 is initiated into operation upon flip-flop H₁ being switched true, clock pulses are produced by output clock 215 which are fed to one input of each of "AND" gates 216, 217, 218, and 219, as shown in FIG. 7. Since column counter 105 has been reset to its zero count K₀ by signal J_8 of character counter 105, "AND" gate 219, to which K₀ is fed along with the clock pulses of output clock 215, will permit the clock pulses to pass therethrough to the "advance" (Y) input of column counter 105 by way of "OR" gate 107. As mentioned previously, column counter 105 is constructed and arranged so that signals applied to its "advance" (Y) input cause counter 105 to count consecutively. Thus, the first clock pulse from output clock 215 will pass through "AND" gate 219 and "OR" gate 107 to advance column counter 105 to count K₁. As a result, the respective transistor 137 of count K₁ will be turned on to effectively ground read column drive line 135, causing full select read current to flow therethrough, since read transistor 151 has already been turned on by H₁. Thus, the five-digit binary number stored in the first column of cores of

array 200, which corresponds to the character in the row adjacent the reference mark 46 (FIG. 2), will be read out of the array 200 to provide respective sense amplifier output signals S_1, S_2, S_3, S_4 , and S_5 , respectively corresponding thereto. As mentioned previously, the presence of a pulse in one of the sense amplifier signals S_1, S_2, S_3, S_4 , and S_5 indicates a binary "1" stored in the corresponding core of the selected column, while the absence of a pulse indicates a binary "0" stored therein.

The sense amplifier signals S_1, S_2, S_3, S_4 , and S_5 , representing the character in the row adjacent the reference mark, which are thus obtained as a result of the first clock pulse of output clock 215, are then fed to output equipment 252 through respective "AND" gates 182, 184, 186, 188, and 190 (which are enabled, since H_1 and E_8' fed to "AND" gate 299 are both true). In addition to being outputted, these signals S_1, S_2, S_3, S_4 , and S_5 are also fed through "AND" gates 172, 174, 176, 178, and 180 (which are enabled, since H_1 and K_1 feeding "AND" gate 220 are both true) and then through respective "OR" gates 112, 114, 116, 118, and 120 to cause flip-flops M1 to M5 to be set up in accordance therewith.

With outputs M1 to M5 of flip-flops M1 to M5 thus set up in accordance with the first character in the row adjacent the reference mark, the outputs M1 to M5 thereof are next applied to output logic circuitry 275 through respective "AND" gates 192, 194, 196, 198, and 200a (which are enabled since H_1 and E_8' fed to "AND" gate 203 are both true). A true output is then caused to appear at one of the three outputs ($|\square|$), (P), or (Y) of output logic circuitry 275, the particular one of the three outputs ($|\square|$), (P) and (Y) which is caused to be true being determined in accordance with the settings of flip-flops M1 to M5, which settings will represent the corresponding characters " $|\square|$ ", "P", or "Y". For example, as explained in connection with FIG. 2, if the settings of flip-flops M1 to M5 represent the character " $|\square|$ ", indicating that the first character in the row adjacent the reference mark is an " $|\square|$ ", as in row 44 of FIG. 2, the ($|\square|$) output of output logic circuitry will become true.

All of the above occurs in response to the first clock pulse provided by output clock 215, as a result of which column counter 105 was advanced to count K_1 . Since the outputs ($|\square|$), (P), or (Y) of output logic circuitry 275 are fed to respective "AND" gates 216, 217, and 218, the only one of these "AND" gates which will be enabled when H_1 becomes true is the one corresponding to the character adjacent the reference mark. Thus, after the first clock pulse, the following clock pulses provided by output clock 215 can pass only through the enabled "AND" gate to the correspondingly labeled "advance" input of column counter 105. For example, if output ($|\square|$) of output logic circuitry 275 becomes true because the character " $|\square|$ " is adjacent the reference mark, as in row 44 of FIG. 2, the clock pulses following the first one will be fed only to "advance" input ($|\square|$) of column counter 105.

Column counter 105 is constructed and arranged so that each of the advance inputs ($|\square|$), (P), and (Y) thereof causes counting from the first count K_1 in a different predetermined manner, all of which, however, have K_9 as the final count. The advance input (Y), for example, causes counting in consecutive numerical order, that is, K_1, K_2, K_3, K_4 , etc. The advance input (P), on the other hand, may provide for counting in the reverse order $K_1, K_8, K_7, K_6, K_5, K_4$, etc. to K_0 . As a further variation the advance input (Y) may permit counting K_2, K_4, K_6 , and K_8 , followed by K_1, K_3, K_5, K_7 , and K_9 . It will be noted that, since the zero count K_0 of column counter 105 is fed to "AND" gate 219, after the first clock pulse of output clock 215 passes therethrough to advance column counter 105 to count K_1 , no further clock pulses will be able to follow this route. Thus, the counting of column counter 105 will be determined only by the "advance" input ($|\square|$), (P), or (Y) effectively selected by output logic circuitry 275.

It will now be understood that, as column counter 105 counts in response to each clock pulse, the column of cores in array 200 corresponding to each count will be outputted to output equipment 252 in the same way as described for the column of cores corresponding to count K_1 . However, it will be noted that "AND" gates 172, 174, 176, 178, and 180 are enabled only during count K_1 because of K_1 being fed to "AND" gate 220 along with H_1 . Thus, flip-flops M1 to M5 will remain set to the first character in the row, and the particular output ($|\square|$), (P), or (Y) of output logic circuitry 275 which is selected in accordance therewith will remain true during the counting operation. It will also be noted that since N_1' remains false during outputting, no pulses can appear in signals A_1, B_1, C_1 , or D_1 , and flip-flop G1 will thereby remain false to prevent program counter 80 from cycling and interfering with character read-out. It will be appreciated by those skilled in the art that, by permitting the read-out of the characters on each row to be determined in accordance with a particular one of the characters on the row, as just illustrated, the versatility of the system is significantly increased. In addition, a considerable reduction in outputting time is possible, particularly where only a portion of the characters on each row are required by the output equipment 252. It will be appreciated that the repetition rate of the clock pulses provided by output clock 215 will ordinarily be chosen in accordance with the operating rate of output equipment 252.

As noted previously, count K_9 will be the final count of column counter 105, regardless of which "advance" input is selected, and is thus conveniently used to return the system to normal scanning operation, since outputting will have then been completed. This is accomplished by feeding count K_9 to "AND" gate 201 along with H_1 , the output of "AND" gate 201 being in turn fed to the reset input h_1 of flip-flop H1. When count K_9 becomes true, it passes through "AND" gate 201 (since H_1 is also true) to switch flip-flop H1 back to the false state in which it resided before outputting. As a result, motors 13 and 40 will be caused to rotate normally again and scanning will continue from where it was halted when signal B_R' became true. Since aperture 22b is thus between two adjacent rows of characters when scanning is resumed, the system will remain inactive until aperture 22b intercepts the reference mark of the next row, at which time, the reference mark signal B_R will reset column counter 105 back to its zero count K_0 . Scanning of this next row and each following row then proceeds in the same manner as has been described above.

Having described the normal operation of the character recognition unit 250 of FIG. 7, the operation thereof when an error is detected will next be considered. For this purpose it will be assumed that a "read" scan has been performed in scanning a particular one of the characters in a row during program counts P_0 to P_{13} , but the settings of flip-flops F1 to F10 do not represent a valid character combination, so that an error is indicated. In such a situation, code converter 110 is constructed and arranged to remain inoperative even though signal 119a is true, thereby causing flip-flops M1 to M5 to remain at their "0" settings. In addition, no code correct signal V_c is provided. Instead, code converter 110 provides a code error signal V_e to indicate that an error has occurred during a "read" scan. As will be appreciated by those skilled in the art, logical circuitry for combining signals F1 to F10 and signal 119a to provide the error signal V_e and to prevent conversion can readily be incorporated in code converter 110. Such typical circuitry is illustrated in FIG. 9 and will be described in detail further on in this specification.

The code error signal V_e thus generated is fed to the "advance" input of an error counter 230 and to one input of an "AND" gate 231 along with the inverted error count signal E_8' , the signal E_8 becoming true in response to the eighth code error signal V_e applied to error counter 230. Thus E_8 will be true to permit each of the first

eight code error signals V_e to pass through "AND" gate 231 and "OR" gate 233 to the set input q_1 of flip-flop Q1 to switch flip-flop Q1 to the true state. When this occurs, Q1 becomes true while Q_1' becomes false causing a reversal in the direction of motor 13 (FIG. 3) thereby reversing the direction of movement of the tape 12; however, since flip-flop H1 is still off, motor 40 will continue to rotate normally and, thus, scanning will continue, but will now progress in the backward direction.

Motor 13 will continue its reverse rotation to cause scanning to progress backwardly until signal B_R' , which is applied to the reset input $\bar{q}_1$ of flip-flop Q1, becomes true causing the flip-flop Q1 to switch back to its false state. As mentioned previously, the fact that signal B_R' becomes true indicates that the reference mark has not been intercepted by aperture 22b. When flip-flop Q1 becomes true again, motor 13 will again rotate forwardly, but only after the tape 12 has been backed up to a position such that the row having the error will be re-scanned again, just as if it had never been scanned; that is, tape 12 is backed up to a point such that aperture 22b will not yet have intercepted the reference mark of the row. As mentioned previously, because of the inherent sloppiness provided in the tape transport 14 and the inertia of motor 13, the re-scan can be expected to be different. Consequently, if the character was misread because a portion of the character was absent, such as illustrated by the character "7" in row 52 of FIG. 2, it is quite possible that, when a "read" scan is again indicated, during the re-scan, the position of the character "7" will be such that the portion of the vertical segment of the character "7" which is present will now be intercepted to permit the character to be properly read.

It should be noted that those characters in the row which have already been correctly read and, thus, are recorded in their respective columns of cores in array 200, are not disturbed during this error detection and, therefore, need not be re-read during the re-scan. This avoids an error which could occur if one of the previously read characters has a portion missing which would cause an error on the re-scan. It should be noted that since Q_1' is false, "AND" gates 70 and 140 to which Q_1' is fed will be inhibited while motor 13 (FIG. 3) is moving tape 12 backwardly, thereby eliminating unwanted pulses in signals A₁, B₁, C₁, and D₁ and preventing program counter 80 from cycling and interfering with the error detection.

If upon re-scan, the misread character is again read improperly, or another error is detected, a second signal V_e is produced by code converter 110 to advance error counter 230 to its second count and again switch flip-flop Q1 to the true state, whereupon the above described operation repeats all over again. If, after eight re-scans a row still cannot be properly read, error counter 210 will have advanced to its eighth count to cause E_8 to be true. E_8' , therefore, will be false, to inhibit "AND" gate 231 so as to prevent further code error signals V_e from passing therethrough to initiate another re-scan. Error counter 230 is constructed and arranged in a conventional manner so that the advance to error count E_8 in response to the eighth code error signal V_e does not occur until after flip-flop Q1 has been switched true by the same code error signal V_e . This assures that the eighth code error signal V_e will switch flip-flop Q1 to initiate the eighth and final re-scan before "AND" gate 231 is inhibited by E_8' becoming false.

The signal E_8' also inhibits "AND" gates 70, 140, and 299, while the signal E_8 resets column counter 105 to zero and enables "OR" gate 123 in the same manner as would the eighth character count J_8 . Thus, scanning progresses forwardly just as if all eight characters in the row were properly read; that is, no further character information will be detected or recorded for the row and, when aperture 22b misses the reference mark, as illustrated in FIG. 6, flip-flop H1 will be switched true to halt

motors 13 and 40 in readiness for outputting. However, because "AND" gate 299 is inhibited by E_8' being false, "AND" gates 182, 184, 186, 188, and 190 will also be inhibited, and only binary "0's" will be outputted to output equipment 252 as column counter 105 counts consecutively, which counting occurs as a result of clock pulses from output clock 215 being fed to the "advance" input (Y) of column counter 105 by way of "AND" gate 221, which is enabled by error count E_8 being true. Error count E_8 is also fed to output logic circuitry 275 in any suitable manner so as to prevent operation thereof, the outputs (| $\square$), (P), or (Y) thereby remaining false to prevent clock pulses from output clock 215 from being fed to any other "advance" input of column counter 105, 15 besides "advance" input (Y). When count K_9 for column counter 105 is reached, K_9 will then be true along with H1, whereupon error counter 230 is reset to zero by the output of "AND" gate 229, flip-flop H1 is switched back to its false state by the output of "AND" gate 201, and scanning proceeds to the next row, just as occurred in normal outputting.

An example of a row which cannot be properly read is illustrated by row 54 in FIG. 2 in which the entire lower half of the character "2" is missing; such a character could not possibly be read correctly since the scan along path r_b would always be 00000 for which no character exists in the system.

In addition to detecting an error when a character is misread during a "read" scan, it is desirable that another type of error also be detected. This error is one that could occur if a portion of a character is missing (such as the character "2" in row 54 of FIG. 2) or, if an extreme case of vertical misregistration is present, which might result in a character in the row being missed by all four apertures during a scan. In such a case, column counter 105 would not properly correspond to the position of each character in the row. In order to detect such an error, the inverted column count K_8' is fed to "AND" gate 237 along with the false output N_1' of flip-flop N1 (FIG. 3) and the pulse S produced when the four apertures 22a, 22b, 22c, and 22d leave shroud 24 and enter window 23 to begin a scan. If at least one of the apertures 22a, 22b, 22c, and 22d have properly detected each character in the row, column counter 105 will be at count K_8 . Thus, when more or less than eight characters are detected during a scan K_8' will be true when the pulse S indicating a new scan appeared. If, therefore, N_1' is also true, indicating that the reference pulse was properly intercepted by aperture 22b during the scan of the row, 35 so that eight characters should have been counted, then pulse S will pass through the output of "AND" gate 237 and through "OR" gate 231 to switch flip-flop Q1 true and initiate a re-scan, in which case operation proceeds just the same as if the error were a result of misreading a character, as described previously. It will be noted that since N_1' is false during outputting, as a result of H1 having been switched true when B_R' became true (see FIG. 6), flip-flop N1 will necessarily remain true during outputting and N_1' will remain false to prevent any possible interference occurring during outputting.

Now, referring to FIG. 9, a typical embodiment of the code converter 110 of FIG. 7 is illustrated, showing in particular the logical circuitry by means of which the correct code signal V_c and the error code signal V_e are produced. From FIG. 9, it will be seen that signals F_1 to F_{10} obtained from flip-flops F1 to F10 in FIG. 7 are fed to each of fourteen "AND" gates 301 to 316, each such "AND" gate forming the logical product of a ten-digit binary number representative of a respective one of the 65 characters in the system. For example, "AND" gate 301 forms the product of the ten-digit binary number corresponding to character "0", inverters I being used to invert appropriate ones of the signals F_1 to F_{10} . It will be evident from FIG. 1 and the description of the character 70 recognition unit 250 of FIG. 7, that character "0" is rep-

resented by F_1 to F_{10} being set to the ten-digit binary number 1000110001, the first five binary digits respectively corresponding to a scan of zones U, V, W, X, and Y along path r_t (FIG. 2), while the last five digits respectively correspond to a scan of zones U, V, W, X, and Y along path r_b . Thus, by inverting F_2 , F_3 , F_4 , F_7 , F_8 , and F_9 before they are applied to "AND" gate 301, the output T_0 of "AND" gate 301 will be true only if F_1 to F_{10} are set in accordance with the character "0". In a similar manner, inverters (not shown) are appropriately provided in particular ones of the inputs of "AND" gates 302 to 316 so that each will correspond to a respective one of the other characters in the system. As a result, each of the outputs T_1 , T_2 , T_3 , T_4 . . . T of "AND" gates 302, 303, 304 . . . 316 will be true only when F_1 to F_{10} are set to the character in the system whose product is formed by the "AND" gate respectively corresponding thereto, the subscripts of the "T" outputs indicating the particular character in the system whose product is formed by each respective "AND" gate.

The signals T_0 to T_{10} thus derived in FIG. 9 are each fed to an "OR" gate 350, whose output 350a is in turn fed to an input of an "AND" gate 324 along with the signal 119a, which is the output of "AND" gate 119 shown in FIG. 7. Since the output 350a of "OR" gate 350 is true only when F_1 to F_{10} represent a character of the system, and the signal 119a is true only when a "read" scan has been performed on the character scanned, the output 324a of "AND" gate 324 will be true only when a character has been correctly read during a "read" scan. The output 324a may thus conveniently serve as the code correct signal V_c , as shown.

It will further be seen in FIG. 9 that the inverted output 350a' is fed to one input of "AND" gate 322, while the signal 119a is fed to the other input thereof. Thus, it will be understood that the output 322a of "AND" gate 322 will be true only if F_1 to F_{10} does not correspond to a character in the system (in which case 350a is false and 350a' is true) and if, in addition, the signal 119a is true indicating that a "read" scan was performed on the character scanned so that a proper reading should have been obtained. Output 322a may, therefore, conveniently serve as the code error signal V_e .

The actual conversion of the ten-digit binary representation of F_1 to F_{10} is performed in code converter 110 by means of code conversion circuitry 330, which may be of conventional design. In order to permit conversion of F_1 to F_{10} only when a character has been properly read during a "read" scan, code conversion circuitry 330 is caused to operate only in response to output 324a of "AND" gate 324 becoming true. This is indicated in FIG. 9 by output 324a (which is also the code correct signal V_c) being fed to code conversion circuitry 330 for use as an energization signal therefor.

The foregoing description completes the detailed disclosure of the character recognition system of FIGS. 1 to 9 which system, as described supra, does not provide the character substitution error detection circuit arrangement and apparatus to be described in connection with FIGS. 10 to 12. The description in the section of the specification which follows is directed to the modifications of the foregoing system for preventing the substitution of one character for another in the set of characters shown in FIG. 1.

Character substitution error detection

In the character recognition system disclosed in FIGS. 1 to 9, the possibility of substituting one character for another character of the set shown in FIG. 1 can be avoided by the provision of suitable means for comparing signals generated in any two successive scans of a row of characters whereby discrepancies in corresponding signals of two successive scans can be detected to

produce a character substitution error signal. It is apparent from the system of FIGS. 1 to 9 that the signals generated in two successive scans of the same row of characters should be identical or approximately identical so as to be at least within the horizontal character registration tolerance of the system, as described infra. For example, the leading edge of each character in a row (the segment of each character in zone U, FIG. 1) should occur at the same time in the successive scans which intercept this character leading edge. Consequently, if the electrical signals generated by scanning these segments in the process of scanning a row of characters are recorded and reproduced at a later time in synchronism with the next scanning of the same row, corresponding signals derived from immediately succeeding scans should occur simultaneously. While it is possible to record, reproduce and compare all significant vertical segments of each character, those segments which comprise the leading edges of the respective characters control the timing or clocking of the reading of respective characters. Since this timing is vital to the determination of the lateral spacing between the vertical segments of each character and therefore the proper recognition of the characters; and improper timing is the source of character substitution errors, the preferred embodiment of the present system provides a novel and relatively simple arrangement for detection of character substitution errors by delaying these leading edge signals so as to make them available for comparison one scanning period later. The comparison of these signals is made possible by delaying each of these signals produced by the first of these scans through magnetically recording and reproducing them. The delay produced during the recording and reproduction of these signals is adjusted to be exactly equal to the row of scanning cycle time interval, i.e., the time required to complete a single scan of a row of characters printed on a tape 12 (FIG. 2).

Referring now to FIG. 10 for a more detailed description, the preferred embodiment of the character substitution error detector is shown to include circuit means for comparing pulses WS produced in response to the edge of character input signals G_1 , supplied from flip-flop G1 (FIG. 7), and pulses RS produced in response to signals (recorded pulses WS) reproduced from a magnetic recording signal track 400 on the outer periphery of a drum 20. This drum 20 corresponds to the drum 20 shown in FIG. 3, but modified to include the signal track 400 for recording pulses WS. The input signals G_1 are coupled from the true output of the flip-flop G1 (FIG. 7) to write single shot 420, a monostable multivibrator. The leading edge of this signal G_1 triggers the single shot 420 to provide the pulse WS having a 30 microsecond time duration, for example. This pulse WS is coupled to write head 406 through write drive 405 to be recorded on the signal track 400. The pulse WS is also applied directly to input 408a, one of the two inputs of the exclusive "OR" circuit 408, so as to enable it to be compared with pulse RS which is applied to the other input 408b.

The recorded pulse WS on track 400 is reproduced by read head 410, amplified by read amplifiers 412 and rectified by a rectifier 414 to provide a suitable positive input signal for peak detector 416. In the peak detector circuit 416, the positive input signal is differentiated and its voltage peak is detected. The signal output of the peak detector 416 triggers a read single shot 418 to produce the pulse RS, having a pulse leading edge which defines the precise time of the reproduced character edge signal G_1 in the preceding scan. The output pulse RS of the read single shot 418, is coupled to input 408b of the exclusive "OR" circuit 408 for comparison with the pulse WS which pulse is currently being produced.

If the pulses RS and WS are not coincident in time, this non-coincidence in time will be indicated by an output pulse from the exclusive "OR" circuit 408. How-

ever, the character registration tolerances of the system provide for a 15 microsecond difference, for example, between the times of occurrence of the pulses WS and RS, i.e., between leading or trailing edges of the pulses WS and RS. To provide for this tolerance, any output pulses (FIG. 11(e)) from the exclusive "OR" circuit 408 are coupled to an error holdover circuit 420. Whenever any output pulse (e.g. pulse 430) is produced which is longer than 15 microseconds, the holdover circuit 420 produces a holdover output or error pulse (FIG. 11(f)) indicating an error condition. This error pulse (e.g. pulse 432) is inverted to produce a true high voltage level error pulse (+4 v.) that is applied to "AND" gate 422 (FIG. 10). When two successive scans are being compared, the gate 422 is enabled by an output R_1 of flip-flop R1 to pass the true, high level error pulse. The flip-flop R1 is triggered to a true state by the output of "AND" gate 424 to produce a true, high level output R_1 after the first scan of any row of characters. The "AND" gate 424 is enabled by inputs P_{15} and K_9 from program counter 80 and column counter 105 (FIG. 7) which signals are present at the end of the first scan of the last character of any row being scanned. Thus, after the first scan in which the reference mark 46 (FIG. 5) has been intercepted by apertures 22b and 22c, pulses RS and WS will be compared, i.e., during the second and subsequent scans of any row of characters being scanned.

The flip-flop R1 is triggered to a false state to disable gate 422 and prevent error pulse output resetting from the comparison of pulses WS and RS, by the leading edge of signal B_R' (see FIG. 6) which is present after completely scanning any row of characters. Therefore, it is only after the first scan of any row of characters that the comparison of pulses WS and RS is effective to determine if a substitution error condition exists and the error output is blocked by gate 422 when the scanning of any row of characters has ended. Thus, the scanning of a row of characters is discontinued at the time signal B_R' (FIG. 6) rises to a high level which indicates that the row of characters being scanned has now passed the scanning position at the scanning station 17 (FIG. 3) and any one of the scanning apertures 22a, 22b, 22c, and 22d will no longer scan the leading edges of the characters (FIG. 6) to provide pulses WS for a proper comparison with pulses RS.

Referring now to FIGS. 10 and 11, the operation of the character error detector shown in FIG. 10 will be described in connection with the reading of the characters shown in FIG. 11 to illustrate the detection of character substitution errors. Referring to FIG. 11 first, in FIG. 11(a), the first three printed characters of the row 54 shown in FIG. 2 are shown enlarged and an ink mark 426 has been added to describe the operation of the error detector system of FIG. 10. Also, scan #1 and scan #2 by the four apertures, 22a to 22d, are shown to illustrate two successive scans of these three characters during the scanning of the row 54. In the following description, it is assumed that pulses WS-1 (FIG. 11(b)) produced during scan #1, having been recorded on the signal track 400 of the drum 20, are now being reproduced to provide pulses RS (FIG. 11(c)) for comparison with pulses WS-2 (FIG. 11(d)), being produced by write single shot 402 during scan #2. The pulses RS are applied to the input 408b of the exclusive "OR" circuit 408 for comparison with the output of the write single shot 402, pulses WS-2, produced during scan #2. It should be noted that during scan #1 none of the scanning apertures 22a, 22b, 22c, or 22d intercept the extraneous ink marking 426. However, during scan #2, the scanning aperture 22b does intercept this mark 426 which causes a spurious edge-of-character signal G_1 to be produced which initiates an output pulse WS-2 which, as will be seen later, will cause a character substitution error signal to be produced during scan #2.

Referring now to FIG. 10 for a description of the operation of the system shown therein for detecting errors, the edge of character signals G_1 produced during scan #1 (FIG. 11(a)) are applied to the input of the write single shot 402 to produce pulses WS-1 (FIG. 11(B)) which are recorded on the signal track 400. The recording of these pulses WS-1 by the write head 406 produces a record on the signal track 400 which is reproduced during scan #2. As the characters are scanned during scan #2, the write single shot 402 produces pulses WS-2 (FIG. 11(d)) which are applied to the input 408a of the exclusive "OR" circuit 408. Also, during scan #2 the pulses WS-1, recorded during scan #1, are reproduced by the read head 410, shaped and coupled to the input 408b of the exclusive "OR" circuit as shown by the output pulses RS (FIG. 11(c)) of the read single shot 418. Noting the timing of the pulses RS and WS-2 shown in FIGS. 11(c) and 11(d), it can be observed that a pulse WS-2 is produced on the output of the write single shot 402 as a result of the spurious edge-of-character signal G_1 , generated at the time of scanning the extraneous ink mark 426. This ink mark 426 has not only been detected but also appears to be reading the leading edge of a substitute character "P," instead of the leading edge of the character "0." In consequence, the comparison of the pulses RS and WS-2 in the exclusive "OR" circuit produces an output pulse 430 (FIG. 11(e)) indicating a character substitution error. Since the output pulse 430 has a time duration of more than 15 microseconds, the error holdover circuit 420 is operative to produce holdover output pulse 432 (FIG. 11(f)) which is gated by "AND" gate 422 to trigger flip-flop ES into a true state.

As previously discussed, the "AND" gate 422 has been enabled by the true output R_1 from the flip-flop R1 which has been triggered in the true state by inputs P_{15} and K_9 during information scans prior to scans #1 and #2, and more particularly, flip-flop R1 is triggered into the true state at the end of the first information scan which is the first scan of these characters. A first information scan of characters in a row has been described previously in connection with FIG. 5. Flip-flop ES is triggered back to a false state at the end of each scan by the output of "AND" gate 439 having inputs P_{15} and K_9 .

The flip-flop ES is the character substitution error flip-flop. The true and false inputs E_S and E_S' are coupled to the circuits of the character recognition unit 250, shown in FIG. 7, as follows: (1) signal E_S is applied to the advance input of error counter 230 to count the error, (2) signal E_S is applied to the true input q_1 of the error flip-flop Q1 to provide for rescanning the row of characters, (3) signal E_S is applied to the reset input of the character counter to reset the character counter, and (4) signal E_S' is applied to the "AND" gate 140 to provide for writing characters into the core array 200 in the absence of a substitution error. The operation of these circuits shown in FIG. 7 have been described before in detail in the description of FIG. 7.

The true output E_S is applied to the error counter 230 (FIG. 7) to advance the same and to the true input q_1 of flip-flop Q1 through "OR" gate 233 to provide for backing up the tape 12 and rescanning the characters shown in FIG. 11(a). The leading edge of the true output E_S provides for the advance of the error counter 23 and the triggering of the flip-flop Q1. The false output E_S' of flip-flop ES is applied to "AND" gate 140 (FIG. 7). During any scan in which flip-flop ES (FIG. 10) is in the true state, the "AND" gate 140 will be disabled to inhibit an output 140a which is required to produce write current through transistor 141 for writing the results of reading of any character into the core array 200. Thus, if a character substitution error occurs and the output E_S is high (+4 v.), not only will the error be counted by the error counter 230 but, also, the characters will be rescaned by backing up the tape 12 as set forth in the

description of FIG. 3 and, more important, if the flip-flop ES is set during the read scan of a character, or information scans after the read scan, the absence of the false output E_S' at "AND" gate 140 (FIG. 7) will prevent writing the substitute character into the core array 200.

In the foregoing description, the operation of the character substitution error detector system shown in FIG. 10 illustrates the manner in which a character substitution error is detected as a result of an ink mark 426 being scanned by the character recognition system. In order to illustrate the character substitution errors which would occur, if the error detector arrangement of FIG. 10 were not incorporated in the character recognition system, it is now assumed that scan #2 is a read scan for the printed characters using such a system. Accordingly, the characters shown in FIG. 11(a) would be read as characters "P," "P," and "3." The first printed character of the three characters is read without error, as printed, i.e., character "P"; but the second character "0" is misread as a substitute character "P." This occurs because during scan #2, the ink mark 426 is detected as the leading edge of the next character; and, the leading edge of the printed character "0" in combination with the ink mark 426 is detected as the code for the substitute character "P" (FIG. 1). The other vertical segment of the printed character "0," the segment opposite from the leading edge of the printed character "0" is now misread as the leading edge of the next substitute character "3." The remainder of the substitute character "3" includes the vertical segment in zone U of the printed character "6." The other vertical segment of the printed character 6 (in zone W) is misread as the beginning of another substitute character. Since the characters which are being misread, as a result of the ink marking 426, are codes of characters included in the set of characters shown in FIG. 1, the substitution of characters is not detected by the code checking circuitry shown in FIG. 9, and the substitute characters would be stored in the core array 200 and outputted. The error detection provided by the arrangement of FIG. 10 would have detected such an error and prevented it from occurring.

Thus, to avoid the foregoing errors, the exclusive "OR" circuit 408, shown in FIG. 10, produces an output pulse 430 (as shown in FIG. 11(e)) each time there is a spurious edge-of-character signal G_1 producing an improper comparison between the pulses RS (FIG. 11(c)) and pulses WS-2 (FIG. 11(d)), to thereby indicate an error. The output pulse 430 is applied to the input of the error holdover circuit 420 which produces the pulse 432 shown in FIG. 11(f). The output pulse 432 from the error holdover circuit (FIG. 11(f)) indicates a character substitution error, i.e., a pulse from the exclusive "OR" circuit having a duration of over 15 microseconds.

In addition to detecting ink marks which would produce a character substitution error, the present circuitry also compares the leading edges of characters to determine whether or not a portion of the leading edge of a character is missing due to poor printing, which defect is capable of producing a character substitution error. From the foregoing description, it will be apparent that missing or undetected portions of leading edges of a character will be noted in the comparison of signals produced during successive scans to produce error output pulses.

In the prior discussion of FIG. 10, it was assumed that the drum 20 was rotating in the direction indicated by the solid line arrow and that the read head 410 was reproducing the pulses WS recorded by the write head 406. However, the error detector system of FIG. 10 is adapted to provide error detection when the drum 20 is rotated in the opposite direction indicated by the dashed arrow in FIG. 10 to accommodate scanning of a row of characters 54a on a tape 12a in the direction, as indicated in FIG. 12. While it has not been shown, or described previously, the reference mark 46 (FIG. 2) may be placed at either end of a row of characters. In FIG. 12 the reference mark 46a for the row of characters 54a on

tape 12a is shown on the opposite end from that shown in FIG. 2. This scanning provides for reading tapes of business machines which, in the process of printing, place the reference mark 46a at the opposite end of the row of characters from that as shown in FIG. 2, and as shown by the row of characters 54a on the section of tape 12a in FIG. 12. The row of characters 54a is read while being scanned in an inverted position and the direction of scanning is from left to right across the row 54a. Accordingly, the drum 20 is rotated in the direction of the dashed arrow shown in FIG. 10 to scan from left to right across the row of characters 54a (FIG. 12) as they pass the scanning station 17 (FIG. 3). Since the characters on tape 12a are inverted, the signals B_1 (FIG. 7) are applied to "AND" gates 92, 94, 96, 98, 100 and signals C_1 are applied to "AND" gates 82, 84, 86, 88, 90 to provide the correct code inputs to the code converter 110. In recording pulses WS on the signal track 400 (FIG. 10), in order to provide the same polarity output signals from the read head 410, independent of direction or rotation of the drum 20, the write head 404 records the signals in the opposite polarity from that of the write head 406. The foregoing arrangement has been provided to read particular cash register tapes directly from a tape roll as wound by certain cash registers without first unreeling the tape roll. Accordingly, these particular cash registers print the reference mark 46a on the left side of the row of characters, as shown in FIG. 12.

In order that the read head 410 will reproduce the recorded pulses WS on track 400 at the proper time to provide coincidence of pulses RS and WS at the inputs of the exclusive "OR" circuit 408, the read head 410 is positioned between write heads 404 and 406 and at approximately the same spacing as adjacent sets of scanning apertures 22a, 22b, 22c and 22d. The spacing is slightly less than the spacing of adjacent sets of apertures (e.g. write head 406 is positioned inwardly toward read head 410) to provide an earlier reproduction of the recorded pulses WS, e.g., by a time interval of 15 microseconds, to compensate for the delay in the output circuits for the read head 410, i.e., read amplifiers 412 and peak detector 416. Thus, when the pulses WS, produced by the write single shot 402 in successive scans of a row of characters are consistent; the pulses RS and WS will be applied to the exclusive "OR" circuit 408 simultaneously and no error output pulse will be produced when compared in the exclusive "OR" circuit 408. When, however, an ink mark or other noise produces a spurious edge of character signal G_1 , an error pulse will be produced by the exclusive "OR" circuit 408 and the error holdover circuit 420.

The description which follows is directed to the details of the error holdover circuit 420 which circuit has been described as having the capability of distinguishing between input pulses of less than or greater than 15 microseconds, i.e., a holdover output pulse is produced only if the duration of an input pulse applied thereto is over 15 microseconds. The circuit diagram for the error holdover circuit 420 is shown in FIG. 10a. To illustrate operation of the error holdover circuit 420, the pulse 430 is shown being applied to its input. This pulse 430 has a time duration of over 15 microseconds, therefore, as a result, the error holdover circuit 420 will produce a pulse 432 at its output. The pulse 430 is coupled to the base of a transistor 440 through a pair of diodes including a silicone diode 442 to provide the proper input voltage levels at the base of transistor 440. The pulse applied to the base of transistor 440 is coupled through its collector to the base of a second transistor 444 to turn off transistor 444 and begin the charging of a capacitor 446 through the resistors 448 including an adjustable resistor which is adjustable to control the charging rate of the capacitor 446. The total resistance of resistors 448 is adjusted to charge capacitor 446 to a positive voltage level in 15 microseconds. The voltage of capacitor 446 is coupled to the base of the following transistor 450 to turn

off the transistor 450 to produce the pulse 432 at the output. Thus, the holdover circuit as described above, is capable of being adjusted to produce an output pulse after 15 microseconds or after other time periods as desired. Thus, if an error indication is only desired for longer or shorter input pulses, it is within the capabilities of the system to discriminate between magnitudes of the errors accordingly. In addition, it should be noted that the write single shot 402 and the read single shot 418 can be adjusted to produce output pulses of shorter duration, e.g., 10 microseconds, whereby all vertical segments of characters scanned by the character recognition system of FIG. 3 during predetermined scans can be applied to the input of write single shot 402 (FIG. 10) in order to compare the pulses WS and RS produced by these segments in predetermined successive scans intercepting these segments by apertures 22b and 22c and thereby determine any discrepancies produced in the scanning of characters due to ink marking, missing portions of a character or noise pulses produced during scanning which are capable of producing character substitution errors.

In the light of the above teachings, various additional modifications and variations of the present invention are contemplated and will be apparent to those skilled in the art without departing from the spirit and scope of the invention as defined by the following claims.

What is claimed is:

1. In apparatus for optically translating a character recorded on a record medium;

said character being stylized to have upper and lower spaced portions, each portion having character segments in predetermined position locations; optical scanning means for scanning said record medium and said character a plurality of times in a direction so as to traverse said segments; 35
optical detecting means coupled to said optical scanning means for producing position modulated output signals in response to the sensing by said sensing means of the presence or absence of a segment in each position of said portions, said scanning means and detecting means also producing output signals in response to said signals; means for recording and reproducing said position modulated signals whereby corresponding signals from at least two different scans are produced approximately coincident in time; 45
means for comparing said signals produced in different scans and detecting spurious signals produced by extraneous marks during said different scans which are not approximately coincident in time to 50 produce an error signal; and means responsive to said error signal for automatically initiating a re-scan of said character by said scanning means.
2. In a character reading system, a record medium 55 having a plurality of characters recorded thereon, scanning means for scanning said characters at least a first and a second time and producing electrical signals corresponding thereto, recognition means for identifying a character in response to the electrical signals produced during the scanning of said record medium and said character by said scanning means; means for recording and reproducing only the electrical signals produced during predetermined time intervals of said first scan for comparison with corresponding signals produced during the second scan; detector means for detecting signals being compared including spurious signals produced due to noise which are present in one scan and are not present in 70 the other scan to produce an error signal; and storage means for storing character identification data corresponding to characters identified by said recognition means, said storage means including means coupled to said detector means and responsive to 75

said error signal for clearing character identification data from said storage means.

3. In a character reading system:

a record medium having a plurality of characters recorded in horizontal rows thereon; each of said characters having a leading edge segment for initiating clock pulses for determining the relative position of character segments spaced therefrom; scanning means for progressively scanning the record medium and the rows of characters in a direction parallel to said rows for producing character edge signals indicating the scanning of leading edge segments of the characters; substitution error detector means for detecting spurious character edge signals having no corresponding character edge signals in different scans to produce an error signal, said error detector means including recording means for recording and reproducing said character edge signals whereby corresponding character edge signals produced during different scans are produced during the same respective time intervals; and comparison means coupled to said recording means and said scanning means for comparing corresponding character edge signals from different scans of the same row of characters to produce said error signal upon the occurrence of spurious character edge signals.
4. In a character reading system according to claim 3 in which said recording means includes:

a magnetizable record surface and spaced read and write heads for recording and reproducing said character edge signals for comparison during different scans.
5. In a character reading system according to claim 3 in which the scanning means includes:

a scanning drum having a plurality of uniformly spaced sets of apertures and rotatable in opposite directions for scanning the rows of characters in either of two opposite directions parallel to said rows.
6. In the character reading system according to claim 5 in which the recording means includes:

a magnetizable record surface on the periphery of said drum and several read and write heads positioned adjacent said magnetizable surface and spaced to record and reproduce the character edge signals of said different scans for comparison of the time intervals of said signals when the drum is being rotated in either of said two opposite directions.
7. In a character reading system:

a record medium having a plurality of stylized characters recorded in horizontal rows thereon; each of said characters being stylized to provide a leading edge portion providing a reference for determining the position of the remaining portions of the character; scanning means for progressively scanning said rows in a direction parallel thereto; said scanning means including means for scanning along a plurality of spaced paths during each scan to traverse the leading edge portion of each character in the row being scanned wherein said paths are spaced perpendicularly to said rows; detecting means for producing electrical signals corresponding to the position of the portions of said characters including the character leading edge portions of the row of characters being scanned for timing the signals produced for the respective characters; recognition means for identifying a character in response to predetermined electrical signals detected along at least one of said spaced paths when another of said spaced paths first fails to intercept any portion of the character during a scan thereof, said

recognition means also including means for detecting when said predetermined electrical signals do not correspond to an identifiable character and for producing an error signal in response thereto;

substitution error detector means for detecting when said predetermined electrical signals do correspond to an identifiable character and for producing an error signal in response thereto;

said substitution error means including means for recording character leading edge signals during each scan of a row of characters and reproducing said leading edge signals so as to be coincident in time with corresponding leading edge signals of the following scan of said row; and

comparison means for comparing signals detected as character leading edge portion signals in successive scans and producing an error signal when a pair of corresponding character leading edge signals are not produced in successive scans within an adjustable time period as determined by the character registration tolerances of the character reading system;

means responsive to either error signal for causing said scanning means to automatically perform at least one re-scan of the row which caused said error signal to be produced;

storage means for storing character identification data corresponding to characters identified by said recognition means as a result of scanning of a row by said scanning means; and

means coupled to said storage means for outputting the characters of a row stored therein, said latter means also cooperating with said recognition means and said means responsive to either of said error signals to output an error indication if after a predetermined plurality of re-scans occurring in response to successive error signals a character in the row cannot be identified.

8. In a character recognition system: a printed record medium having a plurality of characters printed thereon; scanning means including a scanning drum having apertures for optically scanning said record medium and producing electrical signals in response to scanning marks on said document; means responsive to only the elec-

trical signals produced near the leading edge portion of each character for producing edge of character signals; a magnetizable record surface providing a signal recording track on the periphery of said drum; means for magnetically recording said edge of character signals on said record surface and reproducing them during the following scan whereby corresponding edge of character signals produced during successive scans should be coincident in time; comparison means coupled to said scanning means and said reproducing means for comparing the time coincidence of said edge of character signals produced during different scans of said characters to detect non-coincidence and to produce an error signal; and means coupled to said comparison means to be responsive to said error signal for performing a re-scan of the characters.
